UNITED STATES PATENT OFFICE.

WILLIAM DOUGLASS, OF PHILLIPSBURG, KANSAS.

SELF-BINDING HARVESTER.

SPECIFICATION forming part of Letters Patent No. 789,010, dated May 2, 1905.

Application filed June 14, 1902. Renewed January 25, 1905. Serial No. 242,607.

To all whom it may concern:

Be it known that I, WILLIAM DOUGLASS, a citizen of the United States, residing at Phillipsburg, in the county of Phillips and State of Kansas, have invented certain new and useful Improvements in Self-Binding Harvesters, of which the following is a specification, reference being had therein to the accompanying drawings.

10 The present invention relates to harvesters, and particularly to that type commonly called "self-binders," such machines being characterized by instrumentalities which take the grain as it falls before the cutting mechanism, 15 convey it to bundling or sheaf-forming devices, which shape it into sheaves of proper size, after which it is tied or bound to complete the sheaf and finally delivered from the harvester in tightly-bound sheaves ready 20 for stacking. It is with the object of improving upon this type of self-binding harvester, and more especially upon the sheaf forming and binding instrumentalities, that I have produced the present construction. The harvester which I have invented is what may be 25 termed a "straw-binder," for the reason that in binding the sheaf or bundle of grain a withe or band of straw is used, such binders being far more preferable than the twine or wire 30 commonly used, not only because of the saving in cost, but also for the reason that danger of fatalities to the stock fed on the grain, due to their swallowing pieces of the cut wire or the lengths of binder-twine, which latter is 35 readily eaten by cattle and accumulates in the form of balls in the stomach with fatal results, is entirely eliminated. Another advantage of the straw-binder for putting up the sheaves is that the grain may be sent through the 40 thresher without the necessity of exercising the extreme care which is imperative when foreign binders, especially wire, are used, to see that they are not fed with the grain to the threshing instrumentalities, any such carelessness on the part of the feeder frequently 45 resulting in derangement of the threshing machinery and more frequently in disastrous fires on account of sparks struck from the wire binder by the rapidly-operated thresh- 50 ing devices, and, furthermore, the wire in

passing through the thresher is cut into short pieces and beaten out thin, so that it mingles with the straw and grain and is easily swallowed by the cattle, with the above-mentioned fatal results.

55 The present harvester comprises as its essential features instrumentalities for taking the grain as it is cut and conveyed to the proper point and forming and packing it into a sheaf or bundle; other devices for compressing and holding the sheaf in readiness for binding; means for forming a part of the cut grain into a withe or binder, which is twisted to give it strength and admit of its ready tying about the sheaf; mechanism to carry this 60 twisted binder and place it in proximity to the sheaf; instrumentalities for laying the binder about the sheaf and giving it a twisting tie to bind and hold the bundle; devices for securing the twisted binder, so that it may not 65 loosen because of rough handling or its own resiliency, and means for throwing the completed and bound sheaf from the harvester after it has been released by the mechanism mentioned above.

75 The action of the machine forming the subject-matter of the present case is entirely automatic, so that after the harvester is once started, the necessary adjustments having been made, the operations from the cutting of the 80 grain to the delivery of the finished sheaf follow each other in orderly and automatic succession, all of the mechanism, however, being under the immediate control of the operator, so that he may whenever desirable throw them 85 into and out of operation or adjust their action to the conditions under which the machine is working.

In describing the harvester reference will be made to the accompanying drawings, which 90 form a part of this specification, said drawings illustrating one embodiment of my invention.

95 In the following description the several mechanisms which are employed in the formation of the sheaf will be described in the successive order of their operation, prominence being given to those parts which are particularly of my invention, while the common and well-known elements embodied in the case for 100

the purpose of setting forth a complete and operative machine—such as, for example, the cutting instrumentalities, the reel, conveyer-apron, &c.—will be described only so far as 5 may be necessary to give a connected and coherent description.

In the said drawings, Figure 1 is a view in perspective taken from the front corner of the harvester at the delivery end thereof. 10 Fig. 2 is a view in perspective taken from the rear corner of the harvester at the delivery end, these two views serving to illustrate the general arrangement of the parts. Fig. 3 is a plan view of the entire harvester with the 15 band-tying mechanism removed. Fig. 4 is a view, on an enlarged scale, similar to Fig. 3, showing the main driving or “bull” wheel and connected parts. Fig. 5 is a view looking from the right, Fig. 3, to illustrate the conveyer and pick-up chains for the band-forming mechanism. Fig. 6 is a cross-sectional view of the part shown in Fig. 5 on line A A looking from the right, Fig. 3. Fig. 7 is a detail view of part of the construction shown 20 in Fig. 5. Fig. 8 is a cross-sectional view on line B B looking from the right, Fig. 3. Fig. 9 is a cross-sectional view on line C C looking from the right, Fig. 3, showing the controlling-levers of the different mechanisms. are detail views of the band-grasping hands at the lower end of the binder-arms. Figs. 74 and 75 are detail front and side views, respectively, of a binder-arm, showing the hands in closed position. Figs. 76, 77, 78, and 79 are detail views showing the supporting plate or frame for the binder mechanism, such plate being mounted on the scaffold which carries the binder. Figs. 80 and 10 81 are detail views of the supporting-shaft and the raising and lowering rack for the binder mechanism. Figs. 82 and 83 are plan and horizontal sectional views, respectively, and Figs. 84 and 85 are side and vertical 15 sectional views, respectively, of the locking mechanism for maintaining the binder devices in raised position. Figs. 86 and 87 are plan views of the band-tucker mechanism, showing the band seizing and tucking mechanism 20 in two different positions. Figs. 88 and 89 are side elevations from opposite sides of the band-tucker mechanism. Figs. 90, 91, 92, and 93 are detail front end views of the tucker proper, showing it in different positions. 25 Figs. 94 and 95 are detail views of the tucking-blade. Fig. 96 is a detail view of the band-folding finger, over which the band is laid by the tucker-blade. Figs. 97 and 98 are side and edge views, respectively, of an 30 operating-cam for the tuck-holding prong of the tucker. Fig. 99 is a conventional view of a twisted band of straw to show the binding twist and tuck which is given to the band by the binder and tucker mechanism. Fig. 35 100 is a detail view on line $b-b$, Fig. 46, looking in the direction of the arrow to illustrate the locking device for the band-twister-operating wheel. Fig. 101 is a detail on line $c-c$, Fig. 46, looking in the direction of the arrow 40 to illustrate the locking devices for the band-carrier-operating wheel. Fig. 102 is a detail view of the band-severing knife and its assembled parts. Fig. 103 is a detail view of one of the sheaf-straddling arms. Fig. 104 45 is a detail view of the separator-board-operating connections. Fig. 105 is a detail view of one of the forked band-carrier arms.

In the detailed description which follows, in which like reference characters refer to 50 like parts in the several views, I shall first describe the general structure of the harvester and of those parts, such as the cutting and conveying mechanisms, as are of common construction and which do not properly relate 55 to the binding operation and shall then take up in orderly succession the various mechanisms which coöperate in the formation and binding of the sheaf, treating each in the order of its operation.

60 Referring to the drawings, and particularly to Figs. 1, 2, 3, and 4, A indicates the main frame of the harvester, said frame being made up of the usual sills and cross-beams to form a rigid supporting-frame for the harvester 65 mechanism. Said frame A is supported on

two wheels, one of which, B, is the main driving or bull wheel and is located centrally of the harvester and provided with the usual traction-teeth on its periphery. Said wheel B serves to support the harvester for 70 the most part, and it also forms the power-wheel from which the various mechanisms are driven. In order to provide for the vertical adjustment of the harvester-frame A to regulate its height from the ground, the said frame 75 is connected with the shaft of the wheel B by means of the yokes b (see Fig. 9) of inverted-U shape having racks on their inner faces, said racks engaging a toothed rotatable sleeve b' on the bull-wheel shaft b^2 , said sleeve b' having a gear-wheel b^3 fixed thereto. Said gear-wheel b^3 is engaged by a worm (not shown) in a suitable boxing b^4 , a cranked worm-operating shaft b^5 being provided by means of which the sleeve b' may be rotated and the 80 frame A raised or lowered relative to the wheel B and its height from the ground regulated. The other supporting-wheel C is placed at the end of the grain-table, as shown in Figs. 3 and 5, and supports the said table 85 and the cutting mechanism, which is of any usual or desired type, being shown in the present case as comprising the cutter-bar c' and the reciprocating saw-toothed type of cutter-blade c , said blade being reciprocated by the 90 crank c^2 , carried by a shaft c^3 , provided with a pinion c^4 , which meshes with a pinion c^5 on a stub-shaft c^6 , which latter is driven by a drive-chain c^7 , passing over a sprocket-wheel b^6 on the bull-wheel B. Said wheel C is 100 mounted in an adjustable hanger c^8 , pivoted at c^9 to the harvester-frame, said hanger c^8 being raised or lowered to secure vertical adjustment of the wheel C relative to the harvester-frame by means of a rod c^{10} , connected 105 at one end with straps c^{11} on the hanger c^8 , the other end of said rod c^{10} passing through a box c^{12} on the frame of the machine and having a hand-nut c^{13} threaded thereon by which the rod c^{10} may be operated. 110

To the right of the main driven wheel B, Figs. 3 and 19, are placed the grain conveyer and elevator mechanisms, these being of usual construction and comprising the slatted conveyer-apron having a horizontal run D, which 115 receives the grain as it falls before the cutting apparatus and carries it toward the sheaf-forming mechanism at the other end of the binder, the inclined run D' of the conveyer-apron elevating the grain and dropping it over 120 the ridge of the harvester-frame to the sheaf-forming and packing devices. Said conveyer-apron is mounted in the usual way on shafts d , which are connected with the shaft c^3 by driving-chains d' . A suitable grain-reel D^2 125 to sweep the grain down upon the conveyer-apron is provided, said reel having driving connections with the power instrumentalities to receive it. The beater-roll D^3 and the rods D^4 keep the grain against the inclined run D' 130

of the conveyer-apron, while the usual butting-board operated from the upper elevator-shaft through the mechanism D⁶ (see Fig. 17) is provided to trim the grain as it passes up the apron. The usual lifting-lever D⁶ (see Fig. 8) is provided to raise and lower the front of the harvester and the cutting mechanism, the reel-operating lever D⁷ being also shown in Fig. 8, all within reach of the operator's seat, as shown.

Having described those parts of the harvester which are common to such machines, I will now proceed with a description of those mechanisms which constitute my improvements, considering each in order of its operation from the point where the cut grain is first taken to form the withe or band for binding the sheaf to the point where the bound and finished sheaf is ready for delivery from the machine.

The detailed description of the various mechanisms may well be prefaced by the statement that all of the several mechanisms are driven from one main shaft X, which will be referred to hereinafter as the "main driving-shaft," said shaft X receiving its motion from the main driving-wheel B through the pinion c⁵⁰, which is splined to the stub-shaft c⁶⁰ (see Fig. 4) and engages a gear-wheel X', mounted on the shaft X and provided, as shown in the present case, with three series of gear-teeth X², with any one of which series said pinion c⁵⁰ may be caused to mesh by sliding said pinion along the stub-shaft c⁶⁰ by means of the pinion-operating device shown in Figs. 9 and 10, said device comprising a rocking rod x', having a forked arm x² engaging the said pinion c⁵⁰, said rod x' being rocked by means of a hand-lever D⁸, connected by a rod x³ with the said rocking shaft x', (see Figs. 9 and 10,) so that different speeds may be imparted to the main driving-shaft X from the main driving-wheel B, as will be apparent.

The band-straw carrier.—At the extreme right of the harvester, Figs. 3, 5, 6, and 7, is placed the carrier or conveyer which makes the initial step in the formation of the withe or band for binding the sheaf. This mechanism comprises a conveyer belt or apron E, mounted on suitable shafts e, one of which is driven by a chain e', connected with a sprocket-wheel e² on a shaft E', which has a pinion e³, meshing with a gear-wheel e⁴ on the main driving-shaft X of the harvester. (See Fig. 4.) The said belt E travels in the direction of the arrow, Fig. 3, between two vertical separator-boards E² E³, which project forwardly of the cutting apparatus (see Fig. 3) and serve to direct to the conveyer-belt E the grain which is to form the band or withe. The said boards E² E³ are provided at their forward ends with vertically-adjustable portions e⁵, which are hinged at e⁶ to the main part of the boards, so that the said movable portions e⁵ may be adjusted to give them greater or less

dip relative to the main boards, so as to regulate their height from the ground. This adjustment is secured by means of the screw-threaded rods e⁷, (see Fig. 7,) which are provided with suitable adjusting and lock nuts 70 at their screw-threaded ends. At the forward ends of the movable sections e⁵ of the vertical boards are mounted small caster-wheels e⁸, which serve as riders for the forward ends of the conveyer-boards as well as the cutting apparatus. One of the separator-boards, E², is pivoted vertically at its rear end (see Fig. 6) upon a vertical pivot-rod e⁹, so that the said board E² may be swung toward or away from the other division-board, E³, to vary the amount 80 of grain directed to the conveyer-belt E, and so increase or diminish the width of the swath between the separator-boards to allow for the varying run of the grain, to the end that a binder or withe of uniform size may be produced. Said separator-board E² is adjustable from the operator's seat by means of the hand-lever D⁹, which is connected by rod d² with a bell-crank lever d³, from which a rod d⁴ runs to the separator-board E², (see Figs. 3, 8, and 90 104,) so that the latter may be readily swung to and from the other board E³. As it is essential that the grain which is to form the band be laid upon the conveyer-belt E in straight condition in order that swamped or fallen grain may not be fed to the conveyer-belt E in tangled condition, the said separator-boards E² E³ are provided with pick-up chains e¹⁰, said pick-up chains running over small sprocket-wheels at the forward ends of the 100 movable sections e⁵ of the boards and at their rear ends passing over driving-sprockets e¹¹, said driving-sprockets being driven by means of drive-chains e¹⁰³, running over sprocket-wheels e¹⁰⁴ on the shaft E', said pick-up chains 105 being provided with spurs or projections e¹², which will raise the fallen grain and straighten it for entrance between the separator-boards. The said pick-up chains run loosely on sprockets in order that the vertically-movable sections e⁵ may be adjusted without affecting the tension of the chains, and the lower runs of 110 said pick-up chains pass over idler devices e¹³. (See Figs. 5 and 7.) In order to prevent the standing grain at the edge of the swath from 115 becoming entangled with the supporting-wheel C' of the harvester-frame at the cutting end of the machine, a guard rail or rod e¹⁴ (see Fig. 3) is provided, said rod being bowed outwardly, as shown, and serving to 120 push back the standing grain and keep it out of contact with the harvester-frame and the working parts.

The band-straw-compacting devices.—At the rear end of the conveyer-belt E is a straw-receiving trumpet or spout F, (see Figs. 3, 21, and 22,) said spout at its receiving end being the full width of the conveyer-belt E and being provided with an upwardly-flaring mouth, while its rear or delivery end is nar- 130

- rowed or reduced, as shown in Figs. 21 and 22, the side walls of the spout at the delivery end being cut away, as shown, to permit the straw to pass readily to the grasp of the 5 pressing-chains, presently to be described. The straw passes from the conveyer-belt E, upon which it has been laid in straight and orderly manner by the separator-boards and pick-up devices described, into the flaring 10 mouth of the spout F, and passing out of the slightly curved rear end of said spout is seized by carrying and compressing chains f f', which are driven by sprocket-wheels f², mounted in suitable bearings on the machine- 15 frame, one of said sprocket-wheels being driven by means of the gear-wheel e⁴, which meshes with a pinion f³ on the sprocket-wheel shaft, the other sprocket-wheel f² being geared to the driven sprocket-wheel by means 20 of the gear-wheels f⁴. (See Fig. 11.) At their other ends the said chains f f' run over idler sprocket-wheels f⁵, mounted on the board or table f⁶, which carries the said compressing-chains and their associated parts. The inner 25 or straw clamping and compacting runs of the chains f f' pass between the vertical guide-strips f⁷, (see Figs. 3 and 21,) mounted on the table f⁶, said guide-strips serving to hold the chains together in close compacting position, 30 so as to shape the straw fed to them from the spout F, while the outer runs of the chains f f' ride along slightly-raised guides f⁸ on the table, (see Figs. 3, 8, 9, and 21,) which are straddled by the peculiarly-shaped links of 35 the straw-compressing chains. The said chains f f' are made up of what may be termed "carrier-links" and plain connecting-links intermediate the carrier-links. The said carrier-links f⁹ are shown in detail in Figs. 23 40 and 24 and are characterized by lugs f¹⁰, projecting from the side members of the links at right angles thereto, said lugs f¹⁰ embracing the intermediate connecting-links f¹¹ when the chains grasp the straw as it comes from 45 the spout F, and so form interlocking straw carrying and compressing chains which completely inclose the straw and prevent its escape from between the chains, the two chains f f' being so arranged as that each carrier-link f⁹ 50 is opposed to and interlocks with a plain connecting-link of the other chain when the chains come together. The said chains f f' and the conveyer-belt E are so timed as that their travel is synchronous in order that the straw 55 may pass from one to the other in an even continuous strand without any pulling or jamming, the narrow reduced end of the spout F projecting between the chains f f', with the lugs f¹⁰ straddling the end of the spout, as 60 shown in Fig. 21, so as to feed the straw directly to said chains. To guard against danger of the straw becoming entangled with the outer chain f', due to the ends of the straw sticking through the open links of the chain 65 as it passes from the spout F, I preferably cover said links by means of spring-plates f¹², which are secured at their rear ends to the links, as shown in Figs. 23, 24, and 25, said plates f¹² being thrown outwardly by the action of the links as the chains pass over the 70 sprocket-wheels (see Fig. 26) at the delivery end of the carrier and serving to direct the straw to the twister-spout, presently to be described, by springing away slightly from their links as the chain rounds the sprocket-wheel 75 f² and breaking any beards or straw that may have become caught in the chain, thus preventing the straw from being carried around the sprocket-wheels with the chain instead of passing to the twister-spout. If desired, the 80 chain f may be similarly covered; but as the straw does not feed against said chain from the spout F as it does against chain f' such covering is not deemed necessary.
- The band-twister.*—As the compacted straw 85 passes from the delivery end of the compressing-chains just described it enters a cone-shaped spout G, which will be hereinafter termed the "twister-spout," said spout being supported on a suitable bracket (see Figs. 3, 27, 90 and 28) and being composed of a fixed section g and a section g', pivoted thereon at g¹⁰¹ and normally held in the closed position shown in Figs. 27 and 28 by a spring g², secured to the section g and bearing upon a lug g³ on the 95 movable section g', this construction permitting the spout G to yield and accommodate itself to variations in the band-straw coming from the compressing-chains. The coned spout G tends to preserve the compacted form 100 of the straw and said straw issues from the small end of the spout in closely-compacted form, where it is seized by the twister-head proper, which will now be described.
- Hung from suitable tracks H (see Figs. 3, 105 12, and 50) is a twister-carriage, said carriage being supported by means of the horizontal arms H', provided with antifriction-rollers h¹⁰¹ at their ends. Depending from the said supporting-arms H' are hangers h h', on which 110 the twister-head proper is mounted. Said head comprises the band-straw-grasping jaws h² h³, having toothed gripping-faces (see Figs. 47 to 59, inclusive) to insure a tight hold of the straw, and in order to direct the straw to the grip of the jaws h² h³ the said jaw h² is 115 provided with an overlapping forked member h⁴, which straddles the end of the band-straw as it issues from the twister-spout G. The said twister-jaws h² h³ are pivoted at the end 120 of the twister-shaft H², which is rotatably connected with a rotatable collar h⁵, mounted in the hanger h' and provided with a pinion h⁶, by means of which said collar and the twister-head may be rotated. The said pinion h⁶ is in mesh with a gear-wheel h⁷, mounted in stub-shaft h⁸ supported in a bearing carried by a strut h⁹, the ends of which are secured to plates H³, adjustably mounted on 125 the hangers h h' of the twister-carriage, (see 130

Figs. 47 to 50, inclusive,) so that by adjusting the plates H^3 by the slot-and-bolt connections with which they are secured to the hangers h h' the shaft h^8 may be raised or lowered to 5 permit gear-wheels h^7 of different sizes to be used, and thus secure such different speeds for said shaft h^8 and its driven parts as may be desired. At its outer end said stub-shaft h^8 has a small gear-wheel h^{10} , which meshes with 10 a rack h^{11} , fixed to the machine-frame, so that as the twister-carriage is moved back and forth by mechanism presently to be described the said stub-shaft h^8 will be rotated. The gear-wheel h^7 is loosely mounted on the shaft 15 h^8 and is rotatably connected therewith by means of a spring pawl or latch h^{12} , mounted on a collar h^{13} , fixed to the shaft h^8 , (see Figs. 48, 50, 54, and 55,) said pawl engaging a ratchet h^{14} on the said gear-wheel h^7 . The 20 result of this construction is that when the shaft h^8 is turned in one direction by the engagement of the gear h^{10} with the rack h^{11} the said gear-wheel h^7 will be rotated and the twister-head driven. Rotation of the shaft 25 h^8 by the pinion h^{10} in the opposite direction upon the return movement of the twister-carriage will not affect the gear-wheel h^7 , the pawl h^{12} trailing idly over the ratchet h^{14} .

The opening and closing of the twister-jaws h^2 h^3 to grip and release the band is effected in the following manner: As has been stated, said jaws are pivoted at the forward end of the twister-shaft H^2 , (see Fig. 47,) said jaws having stiff springs h^{14} , tending to close 30 the jaws, the springs h^{14} bearing at their rear ends against the inner periphery of the collar h^5 to give them the desired tension. The jaws h^2 h^3 are further provided with rearwardly-projecting tailpieces h^{15} , which are 35 engaged by a sliding cone or cup h^{16} , mounted on the shaft H^2 , a spring h^{17} tending to press said cone h^{16} forward to the position shown in full lines, Fig. 47, in which position of the cone the jaws h^2 h^3 will be held in the 40 full-line open position shown. The said sliding cone h^{16} has a yoke h^{18} secured thereto, said yoke being mounted at its upper end on a sliding rod h^{19} between adjusting-nuts, as 45 clearly shown in Fig. 47, said rod being slidingly mounted in suitable ears on the hangers h h' . At one end of said sliding rod h^{19} is an upwardly-projecting arm h^{20} , which 50 strikes a projection or stop h^{21} on the machine-frame (see Fig. 3) as the twister-carriage runs 55 forward to the twister-spout G , throwing the sliding rod h^{19} and cone h^{16} to the position shown in dotted lines, Fig. 47, thus releasing the twister-jaws, which are immediately closed by their springs and grasp the end of the 60 band projecting from the twister-spout G . A pin h^{22} on the said rod h^{19} engages and rides in a guard-loop h^{23} on the carriage-frame, so as to prevent the rod h^{19} from turning in its supporting-ears and insuring the retention of

the arm h^{20} in proper position to be struck by 65 the stop h^{21} at all times. When the rod h^{19} and cone h^{16} are moved to the position shown in dotted lines in Fig. 47 by the operation just described, they are locked in such position by means of a spring-bolt h^{24} , mounted 70 on the carriage-frame and resting at its lower end upon a locking-plate h^{25} on the said yoke h^{18} , said locking-plate having a hole h^{26} therein, into which the bolt h^{24} drops as the plate h^{25} moves back, a guiding-rib h^{27} on plate h^{25} 75 serving to direct the bolt h^{24} to the receiving-hole h^{26} . At its upper end said spring-bolt h^{24} is engaged by a lifting-lever h^{28} , which is pivoted to the carriage-frame, said lever h^{28} being tilted to the position shown in dotted 80 lines, when the bolt h^{24} is forced downwardly to engage the locking-plate h^{25} . The elevated tail of lever h^{28} strikes a roller or other fixed operating device h^{29} on the harvester-frame, (see Fig. 3,) when the twister-carriage reaches 85 the limit of its outward movement, tilting the lever h^{28} , raising the spring-bolt h^{24} from engagement with plate h^{25} , and allowing the rod-yoke h^{18} , rod h^{19} , and cone h^{16} to return to the 90 position shown in full lines, Fig. 47, under the action of spring h^{17} , this movement of the cone throwing the twister-jaws open and releasing the band.

The twister-carriage and the parts mounted thereon, which have just been described, are 95 moved forward and back on the tracks H by means of a cord i , preferably of wire for strength and flexibility, said cord i being attached at either end to turnbuckles i' , adjustably secured to the twister-carriage, as shown 100 in Figs. 47 and 48. The cord i runs over pulleys I I' at each end of the tracks H , pulley I at the outer end of the tracks being an idler-pulley, while pulley I' , about which the cord i makes a complete turn, forms a driving-pulley which is rotated by mechanism, which will now be described, to drive the 105 twister-carriage. The pulley I' is mounted so as to rotate freely upon the main driving-shaft X of the harvester, (see Figs. 11, 12, 46, and 100,) said pulley I' being locked to said shaft X to rotate therewith during certain periods by means of a projection i^2 on the pulley which engages a lever i^3 , carried by an arm i^4 on a collar i^5 , fixed to the shaft X , the 110 inner end of the lever i^3 playing in a slot i^6 in the collar i^5 , while the outer end of the said lever carries a roller i^7 , which at a certain angle of revolution of the arm i^4 rides over a fixed stop i^8 on the harvester-frame, (see Figs. 4 and 46,) tilting the lever i^3 and disengaging it from the projection i^2 and releasing the pulley I' . Surrounding the said 115 shaft X is a torsional spring i^9 , one end of which is secured to the pulley I' , the other end of the spring being secured to a plate i^{10} rotatably mounted on a standard i^{11} , rising from the machine-frame, said plate being ad-

justable to vary the tension of the spring i^9 and being locked in adjusted position against movement by a spring-latch i^{12} on the standard i^{11} . It will be seen that positive rotation 5 of the pulley I' in one direction by the shaft X , to which it is locked by the projection i^2 engaging the lever i^3 to carry the twister-carriage outwardly, will put the said spring i^9 under tension, so as that when the said 10 pulley I' is unlocked from the shaft X by the tilting of the lever i^3 , engaging the stop i^8 , the pulley will be quickly rotated in the opposite direction by the spring i^9 and the return movement imparted to the carriage. 15 The shaft X moves at comparatively slow speed, so that the spring i^9 , which imparts a quick rotation to the pulley I' when the said pulley is disengaged from the arm i^4 , will effect a complete return of the twister-carriage before the projection i^2 meets the lever i^3 on the arm i^4 and again locks the pulley I' to the shaft X , the actual distance through 20 which the twister-carriage travels being considerably less than the circumference of the pulley I' .

Mounted in a suitable support i^{13} on the harvester-frame (see Figs. 3, 29, 30, 31, 32, and 102) is a sliding band-severing knife consisting of a plate i^{14} , sliding freely in the support 30 i^{13} and being provided with a spring i^{15} , which imparts the cutting thrust to said knife. Said plate i^{14} carries at its forward end the severing-knife i^{16} , having a serrated cutting-blade, as shown in Figs. 31 and 32. Said knife i^{16} is pivoted, as shown in Figs. 31 and 32, at the 35 forward end of the plate i^{14} , said plate having connected therewith, by means of a link i^{18} , an operating-lever i^{17} , said operating-lever being provided at its other end with a roller i^{19} , (see Fig. 3,) which engages a cam i^{20} on a collar fixed to the shaft X of the machine, the said cam i^{20} being so timed relative to the travel of the twister-carriage that it will release the operating-lever i^{17} and allow the spring i^{15} to 40 give a severing thrust to the knife i^{16} at the moment when the twister-carriage has reached the limit of its outward movement and has completed the twisting of a band length of straw. The said severing-knife is provided 45 at its point with a lug i^{21} , which normally bears against the under side of the ledge i^{22} , formed on a plate i^{23} , mounted just at the discharge side of the twister-spout, (see Figs. 3 and 29,) said plate i^{23} being provided with an opening 50 through which the band-straw passes from the twister-spout, and it will be seen that the severing-knife i^{16} crosses said opening in the plate i^{23} with a shearing cut. After making this severing cut the knife i^{16} is depressed and 55 passes back to its normal position beneath the band-opening by means of a pivoted spring-held plate i^{24} , pivoted on the plate i^{23} , as shown in Figs. 29 and 102, the lug i^{21} depressing the plate i^{24} in its forward movement, but on its

return movement riding along the lower inclined edge of the plate i^{24} and passing back to its original position, so that the knife i^{16} will clear the continuously-moving band on its return movement, the spring i^{25} (see Fig. 32) throwing the knife i^{16} back to its normal 70 position after it has made its return movement.

At this point it is deemed advisable to briefly outline the operation of the band-forming mechanisms, which have been described in detail in order that the chain of steps performed up to the present point may be clear.

Operation: The conveyer-belt E for the band-straw delivers a continuous quantity of the cut grain to the compressing-chains $f f'$ through the spout F , and the said chains $f f'$ compact and shape the straw into a band and deliver it through the twister-spout G in shaped condition. Assuming that the twister-carriage is in its forward position ready to seize the end of the band-straw as it projects from the twister-spout G , the spring-twister jaws $h^2 h^3$ will be released by the controlling-cone h^6 being thrown back by the upwardly-projecting arm h^9 striking the stop h^{21} on the harvester-frame. The twister-jaws will immediately snap together upon the end of the band, and at this moment the driving-pulley I' will start the twister-carriage on its outward travel along the tracks H . During this outward movement of the twister-carriage the twister-jaws will be revolved through the stub-shaft h^8 , driven by the gear-wheel h^{10} , engaging with the rack h^{11} , the gear-wheel h^7 , which drives the twister-jaws, being locked to the shaft H by the spring-pawl h^{12} . A uniform twist will thus be given to the straw band, it being understood that the travel of the twister-carriage is accurately timed with the travel of the compressing-chains, so that there will be no undue pull on or slackening of the band as it comes from the compressing-chains. When the twister-carriage, with its revolving twister-jaws, reaches its outer position, the band-carrier, which will now be described, comes forward and seizes the band length which has just been twisted by the twisting mechanism, and immediately after the twister-jaws are opened by the lifting-lever h^{27} coming in contact with the fixed roller h^{28} , releasing the cone h^{16} , which immediately slides forward under the action of the spring h^{17} , and, engaging the tailpieces h^{15} of the twister-jaws, throws them to open position and releases the outer end of the band. Simultaneously with the releasing action of the twister-jaws the severing-knife i^{16} at the twister-spout makes its severing cut, and a twisted band is now held by the band-carrier ready to be delivered to the sheaf.

The band-carrier.—Mounted on inclined tracks J (see Figs. 3, 12, 62 to 65, inclusive,) are the band-carriers, two being shown, one upon

each track, said band-carriers being similar in construction. The said band-carriers comprise two sliding frames J' , mounted upon the said tracks J , said frames J' being connected 5 with chains J^2 , mounted on sprocket-wheels J^3 , secured to suitable shafts on the frame of the machine. Secured to each of the said sliding frames J' are two band-grasping jaws $j j'$, the lower jaw j resting upon the track J 10 and preferably being a continuation of the said sliding frame J' , as clearly shown in Figs. 62 and 63. The upper jaw j' is pivoted at its end to lugs j^2 , carried by the sliding frame J' , and the said upper jaw has on its 15 outer side a roller j^3 , which as the band-carrier slides rearward on its tracks rides over a movable rod j^4 , pivoted, as shown in Figs. 3, 12, and 66, to projections j^5 at the extreme rearward end of the band-carrier tracks J . 20 As the said roller j^3 rides up the inclined rods the upper band-grasping jaw j' will be thrown to its open position, as shown in Fig. 63, this opening of the band-carrier jaws taking place as the band-carrier reaches its extreme 25 rearward position, so that the open jaws will straddle the twisted band. At this point the roller j drops off the rearward end of the inclined rod j^4 and the band-carrier jaws j and j' grasp the twisted band at each end. 30 The upper jaw j' is thrown down and held with a spring gripping action against the lower jaw j by means of a spring j^{101} , which is secured to the lower jaw j at one end and bears at its free end on a pin j^{102} , projecting from a 35 hanger j^{103} on the upper jaw j' , Figs 62 to 64. In order to firmly lock the twisted band between the band-carrier jaws $j j'$, a pinching-finger j^6 is provided, said finger being pivoted to the upper jaw j' , as shown in Figs. 40 62 and 63, the end of said pinching-finger being connected, by means of a link j^7 , with an arm j^8 , pivoted at its rear end to the lower band-grasping jaw j . At its forward end the said arm j^8 is provided with a link j^9 , which 45 is pivoted to the forward end of a clamping device mounted upon the end of a bail j^{10} , which connects the two band-carriers, as shown in Fig. 3, an intermediate link j^{11} connecting the said arm j^8 with the upper band-grasping jaw 50 j' . It will be seen that as the band-carrier starts on its return movement the band-grasping jaws $j j'$ and the band-pinching finger j^6 will remain in closed position and will not be affected by the jaw-opening rod j^5 , for the reason that the roller j^3 will ride back beneath the said rod j^4 , the rod rising idly to its dotted-line position without affecting the said band-grasping jaws. The said bail j^{10} is provided with two forked supporting-arms j^{12} , 55 (see Figs. 3 and 105,) upon which the twisted band will rest, the center of the bail j^{10} having an offset supporting portion j^{13} to sustain the band at its middle, and as the jaws $j j'$ open and close the bail j^{10} is alternately dipped 60 and raised by the movement of the clamping 65

device, which connects the jaws and the bail, so that as the band-carrier goes rearward and the jaws open the bail j^{10} dips beneath the middle of the band, and as they close the bail is lifted to uphold the band at its middle. 70

The band-carrier just described is operated by the following means: The carrier-chains J^2 , above referred to, run over the sprocket-wheels J^3 , two of which are mounted on a shaft j^{14} , journaled in suitable bearings on the harvester-frame and lying beneath the band-twister tracks, (see Fig. 4,) while the other two sprockets J^3 are carried by stub-shafts j^{140} , secured to the harvester-frame. This shaft j^{14} and its sprocket form the operating 80 means for moving the band-carrier along its tracks, motion being imparted to the said shaft j^{14} by means of a chain j^{15} passing over a sprocket j^{16} on the shaft, said chain being driven by a large sprocket-wheel j^{17} , (see Figs. 85 4, 11, 46, and 101,) carried by a shaft j^{18} , suitably journaled on the harvester-frame. At the other end of the said shaft j^{18} is a small pinion j^{19} , which is intermittently engaged and rotated in opposite directions by two opposed 90 and angularly-offset segments $j^{20} j^{21}$, mounted on the main driving-shaft X . The said sprocket-wheel j^{17} is provided with a spring locking-latch j^{22} , mounted on a fixed standard j^{23} , said latch j^{22} engaging a suitable notch or 95 projection on the rim of the wheel j^{17} , so as to hold the said wheel locked against rotation until the latch has been disengaged from the locking-notch. The said wheel j^{17} will be held in locked position by its catch j^{22} , while the 100 band-carrier is lying beneath the sheaf in the position shown in Fig. 3, just before the segment j^{21} engages the pinion j^{19} to draw the band-carrier rearward to grasp the band. As the said segment j^{21} comes around to engage the pinion j^{19} a projecting arm j^{24} on the inner face of the segment j^{21} engages a pin j^{25} on the spring-latch j^{22} , and pulling the latch back releases the wheel j^{17} , which is then rotated to drive the shaft j^{14} and the 105 carrier-chains J^2 , so as to draw the band-carrier rearward to take the twisted band, the spring-latch j^{22} trailing over the face of the wheel until it snaps into the notch or behind the projection thereon. It will be understood 110 that the operation of the band-carrier-operating devices are so timed relative to the band-twister, which has been hereinbefore described, that the segment j^{21} moves around the arm j^{24} on the segment j^{21} , unlatches the 115 sprocket-wheel j^{17} , and rotates the said wheel so as to bring the band-carrier into position to grasp the band just as the twister-carriage, with its band-twisting devices, has reached the outward limit of its movement. Immediately 120 the band-grasping jaws seize the band the twister-jaws are released, the band-severing knife makes it thrust and cuts the band at the twister-spout, and at this moment segment j^{20} then comes into engagement with the pin 125 130

ion j^{10} to rotate the sprocket-wheel j^{17} in the opposite direction, returning the band-carrier to its starting position beneath the sheaf, the latch j^{22} snapping into place and holding it until the carrier is to be again moved rearward to seize another band.

Having now described the complete formation of a band and the positioning of it beneath the sheaf, the devices for forming and holding the sheaf during tying will be described.

The sheaf-forming devices.—As the cut grain is raised by the inclined run D' of the main conveyer and elevator belt (see Fig. 19) it falls over the ridge of the harvester and down the inclined grain-deck K. The grain is caught about midway the length of the board K by a swinging substantially U-shaped arm K', the bottom of which is bent at right angles to the arms and passes through a slot K² in the grain-deck K, so that in this position it will catch the grain as it slides down the grain-deck and cause it to accumulate. The said U-shaped arm K' is carried by a rocking bar k, hung in suitable supports on the scaffold of the harvester (see Fig. 2) and is provided at one end with an operating-arm k', connected, by means of a link k², with a lever k³, pivoted to the scaffold, said lever being operated by means of a projection k⁴ on a shaft which forms the power-shaft of the band-tying devices, which will be hereinafter described, a suitable stop k⁵, against which lever k³ strikes, (see Fig. 20,) being provided to prevent the arm K' dropping too close to the grain-board. It will be apparent that when the projection k⁴ strikes the lever k³ the latter will be tilted and the U-shaped arm K' thrown up, allowing the accumulated grain to escape and slide down the grain-deck K to the sheaf-cradle and packer devices, which will now be described.

The sheaf-cradle is made up of four substantially U-shaped arms, (see Figs. 12, 14, 16, 19, 33, 34, and 35,) two of which arms, k⁶ k⁶, are secured at one side of their centers to a rock-shaft k⁷, mounted on a vertically-sliding frame k⁸, which slides freely in a guide-way k⁹, mounted on a beam k¹⁰ of the harvester-frame. The said arms k⁶ k⁶ are supported by a rod k¹¹, mounted in the sliding frame k⁸ parallel to the shaft k⁷, the frame k⁸ being upheld by a spring-arm k¹², which is secured to a tilting beam k¹³, pivoted on the harvester-frame and tilted by means of a cam k¹⁴ on the main driving-shaft X of the machine, a loop k¹⁵ at the rear end of the beam limiting the upward movement of the rear end of said tilting beam k¹³. It will thus be seen that the two arms k⁶ k⁶, which form one-half of the sheaf-cradle, are mounted on a vertically-movable frame and supported by a rocking shaft, so that they may be raised and lowered and rocked relative to their supporting-frame. The other two arms, k¹⁶ k¹⁶, of the

sheaf-cradle are similarly mounted upon a rock-shaft k¹⁷, (see Fig. 35,) said arms k¹⁶ being supported by rod k¹⁸, carried by the beam k¹⁹; but said shaft is pivoted in bearings at the end of a pivoted beam k¹⁸, pivoted to the machine-frame in the same manner as is the beam k¹³, a cam k¹⁹ being provided on the shaft X to tilt this last-named rocking beam k¹⁸, the cams k¹⁹ and k¹⁴ being similar and imparting similar movements to the rocking beams, except that provision is made for giving one movement to the beam k¹⁸ and its cradle-arms, which is not necessary for the other half of the cradle. The projection k²⁰ on cam k¹⁹ gives a lift to the beam k¹⁸ just at the moment when the band-carrier, hereinbefore described, makes its movements transversely of the machine beneath the sheaf-cradle, this being necessary that the said beam k¹⁸ and its supported parts may be raised out of the way of and not foul and impede the travel of the band-carrier.

Into the sheaf-cradle constructed as above described the grain released by the arm K' is packed by packer-arms k²¹. These packer-arms are arranged in pairs projecting through slots k²² in the grain-board K, (see Figs. 2 and 19,) one arm of each pair being carried by crank-arms k²³ on short shafts k²⁴, mounted in uprights k²⁵, secured to the rocking beams k¹³ k¹⁸, hereinbefore referred to. The other arm of the respective pairs of packer-arms k²¹ is connected to the crank-supported packer-arm by a link k²⁶, and the lower ends of each packer-arm k²¹ are pivotally connected with the rods k²⁷, four in number, which are hung from a supporting-arm k²⁸, depending from the under side of the grain-board K. The said crank-shafts k²⁴ are rotated by means of driving-chains k²⁹, which pass over suitable sprocket-wheels on the shafts k²⁴ and are driven from large sprocket-wheels k³⁰ on a shaft k³¹, which receives motion from a pinion k³², driven by a gear-segment k³³ on the main driving-shaft X of the harvester, a locking-dog k³⁴, carried by a spring-pressed arm k³⁵, engaging said pinion k³² and holding it from rotation until released by means of the flange k³⁶ on the segment k³³ striking the lifting-roller k³⁷ on the arm k³⁵, thus preventing action of the packer-arms except at fixed intervals. In order to catch any straw which might work out at the delivery side of the cradle, a vertically-placed spring-projected catcher-rod k³⁸ is mounted in one of the arms k⁶, said rod normally projecting above the sheaf-cradle, but having a hooked lower end k³⁹ engaging a loop k⁴⁰ on a fixed part of the machine, (see Fig. 12,) so that as the sheaf-cradle is elevated the said rod k³⁸ will be caught by the loop and drawn down out of the way, so as not to interfere with the rotation of the band tying and twisting mechanism as it revolves above the cradle.

From the foregoing it will be seen that the packer-arms k²¹ work with a kicking or ted-

dering movement against the grain as it slides down the grain-board K after being released from the holding-arm K' and pack it down into a close compactly-formed sheaf into the 5 sheaf-cradle.

It is to be understood that the arm K' will remain in its normal position during such a length of time as will under ordinary circumstances permit the accumulation of a sufficient 10 amount of grain to form a sheaf and that it will then rise, allowing the grain to flow to the packers and sheaf-cradle, after which it will again fall for the next accumulation of grain.

15 When the charge of grain for the sheaf has been packed into the cradle by the action of the packer-arms just described, the bundle or sheaf compressor is brought into operation. Said sheaf-compressor comprises a rigid arm 20 M, supported by a sleeve m, carried by a rock-shaft M', (see Figs. 1, 3, 4, 12, 14, 17, 42, and 43,) which is intermittently operated by a gear-segment m', (see Figs. 4 and 17,) supported on the power-shaft X, engaging a gear- 25 segment m² at the end of the rock-shaft M', a sleeve M³, fixed to the shaft M', imparting motion to the compressor-arm M through a torsional spring m²⁰. Secured in a socket on said arm M is a spring compressor-arm M², 30 having at its forward end the spring-yoke m³, adapted to straddle the sheaf when the compressor is forced down by the engagement of the gear-segments m' m² and compress it tightly in the cradle, teeth m³¹ being preferably placed on the inner face of the yoke m³ to bite into and hold the sheaf firmly in the cradle, said teeth serving also as stops to prevent the tucking-blade, which will be herein-after described, from forcing the band out of 35 place as it makes the tuck, as will appear hereinafter. The said spring-arm M² bears with a yielding pressure upon the sheaf as the compressor device first descends, so as to shape and form the sheaf, the rigid arm M bearing 40 upon said spring-arm after its first impact and forming a stop or abutment for said spring-arm. The said sheaf-compressor is locked in its compressing position by means of a spring-latch m⁴, carried by the tilting beam k¹³, (see 45 Figs. 4, 19, 33, 34, 42, 43, and 45,) which engages a ratchet-plate m⁵ on the spring-arm M², said ratchet-plate m⁵ passing into a loop m⁶ at the end of beam k¹³ as the compressor descends, so that the spring-latch m⁴ snaps 50 into engagement with the teeth on plate m⁵. Said latch holds the sheaf-compressor in its lower sheaf-compressing position during the operation of the band tying and tucking devices, which will now be described, and after 55 60 the completion of these steps the latch m⁴ is automatically thrown out of engagement with ratchet-plate m⁵ by a cam projection m⁷, formed on the sheaf-cradle-lifting cam k¹⁴, (see Figs. 4, 19, and 34,) engaging a hook at 65 the rear end of a spring-actuated pull-rod m⁸,

connected at its forward end with the latch-plate m⁴, (see Figs. 33 and 45,) the compressor when released being immediately thrown to its upper position by the action of torsional spring m²⁰, which is put under stress when the said compressor-shaft M' is thrown over by its segment to force the compressor down upon the sheaf. In order to hold the said shaft M' in its compressing position and the spring m²⁰ under stress, the segment m² has a pin m⁹, which snaps past a spring-pin m¹⁰ on the machine-frame as the shaft M' is rocked and the compressor-arm thrown to compressing position, and is locked thereby until released by a projection m¹¹ on the segmental plate p⁷⁰, mounted on the driving-shaft X of the harvester, the action of the spring-pin being so timed as to release the compressor rock-shaft M' at the moment of completion of the tying and tucking of the band about 85 the sheaf.

The band-tying devices.—Mounted on a suitable scaffold rising from the frame of the harvester is the mechanism for tying or twisting the twisted band length which is delivered by the band-carrier, as above described, about the sheaf. The said tying mechanism is supported from a substantially circular plate N, (see Figs. 11, 17, 19, and 67 to 78, inclusive,) secured to transversely-placed angle-irons N', mounted on the scaffold, a second plate, N², being rotatably supported from the plate N by depending lugs n, having anti-friction-rollers, (see Figs. 76 and 77,) so that plate N², with its supported parts, is free to turn. Hanging from said plate N² are guides N³, four in number, having inner grooved faces, the guides N³ of each pair being inclined toward each other at their lower ends, with the respective pairs parallel relative to 100 each other. (See Fig. 2.) Between each pair of guides N³ is placed a second grooved guide N⁴, supported by means of struts or brace-plates n', spanning the guides N³ and serving to steady the up-and-down movements of the 105 tying mechanism, brace-rods n², connected with the scaffold, being provided to steady these guides, as clearly shown in Figs. 2, 11, and 14.

A shaft N⁵, having a rack N⁶ secured thereto, is mounted so as to slide freely centrally of the plates N N², (see Figs. 11, 14, 17, 19, 67, 77, 78, 80, and 81,) said shaft having at its lower end two supporting-ears n³. The said shaft and rack are mounted to slide vertically, being guided by suitable guides n⁴, supported on the binder-scaffold, arms n⁵ on the rack provided with antifriction-rollers running in the grooves of the guides n⁴ and holding the parts vertical. The said shaft 115 N⁵ and rack N⁶ are raised and lowered by means of a gear-wheel n⁶, meshing with the rack, said wheel n⁶ being mounted on a horizontal shaft n⁷, journaled on suitable supports, a pinion n⁸ at the end of the shaft n⁷ 120 125 130

being engaged intermittently by opposed and angularly-offset segments n^9 on a second shaft n^{10} , which is driven by a pinion n^{90} , meshing with a gear n^{91} on a gear-segment N^8 , said gear-segment being mounted on a shaft N^9 , having a sprocket-chain connection n^{11} from the main driving-shaft X of the harvester. The result of this construction is that the said vertical rack N^6 and the shaft N^5 , which supports the band grasping and tying devices, presently to be described, will be raised and lowered alternately as the segments n^9 engage the pinion n^8 and rotate the shaft n^7 and the rack-engaging gear-wheel n^6 . A torsional balancing-spring n^{12} surrounds the shaft n^7 , one end of said spring being secured to the gear-wheel n^6 , while the other end is secured to a fixed part of the frame, so that the said spring n^{12} , which is put under tension on the downward movement of the rising and falling frame, will assist in raising the latter on its upward movement.

Pivoted to the supporting-ears n^3 at the lower end of shaft N^5 are arms n^{13} , said arms having at their upper ends cross-rods n^{14} , provided at their outer end with antifriction-rollers n^{15} , which travel in the grooves of the opposing guideways N^3 of the respective pairs. It will be apparent that as the said arms n^{13} rise and fall with the vertically-moving shaft N^5 and rack N^6 they will open and close by reason of the cross-rods n^{14} riding up and down the inclined grooved guideways N^3 , said arms n^{13} opening at their lower ends as the mechanism descends and closing as it rises, so that when the arms descend they will spread and straddle the packed sheaf which lies in the sheaf-cradle in the grasp of the compressor, all as hereinbefore set forth. Pivoted on arms projecting from the said sheaf-straddling arms n^{13} are the band-grasping hands n^{16} , said hands having the tubular interlocking band-grasping fingers n^{17} . (See Figs. 67 to 75, inclusive.) Said hands n^{16} are normally in the position shown in Fig. 74 with their fingers closed and interlocked, such closed position being induced by the stiff springs n^{18} , secured at their upper ends to the arms n^{13} by means of clamping-plates n^{20} and bearing against pins n^{19} at the lower ends of said hands n^{16} , adjustable fulcrum-screws n^{21} being provided against which the springs bear, thus affording means for increasing their stress upon the band-grasping hands at will. The opening of said normally closed hands is effected by means of sliding frames n^{22} , which are carried by said arms n^{13} , each frame having a dovetailed sliding connection n^{203} with one of said arms, as shown in Fig. 69. Said sliding connecting-piece n^{203} should be of sufficient length to form a strong connection between the parts, but not so long as to interfere with the play of the sliding frames n^{22} , and in Fig. 74 is illustrated a convenient length, in which it is shown as terminating at

its upper end just above the horizontal lower yoke of the frame n^{22} , the lower end of the sliding piece n^{203} , terminating at the lower end of the dovetail channel in the arm n^{13} , as clearly shown in said Fig. 74. Pivoted on said frames n^{22} are guide-plates n^{23} , which are normally held by weights n^{20} , which are carried by integral right-angle projections near the lower ends of arms n^{13} in the position shown in Figs. 68 and 74, with their upper ends resting against stop-pins n^{24} on the frames. The said frames have pull-rods n^{25} connected at their lower end with suitable lugs on the sliding dovetail connecting-piece n^{203} of the frame n^{22} , the upper ends of said rods n^{25} passing through keepers n^{26} on the arms n^{13} , so as to hold the upper overturned ends of the rods in the position shown in Figs. 67, 68, and 74. In this position said rods strike hooks at the lower ends of rods n^{26} as the arms n^{13} and their hands descend to straddle a sheaf and stop the descent of the frames n^{22} , the dovetailed sliding connection between the frames and the arms n^{13} permitting the arms n^{13} to continue their descent. As the arms n^{13} with their pivoted spring-closed hands n^{16} move downwardly after the frames n^{22} have stopped the rollers n^{15} at the upper ends of the hands n^{16} will ride down the inclined guide-plates n^{23} , opening the hands against the action of springs n^{18} as they descend on either side of the sheaf, so that the fingers at the ends of the hands will drop on either side of the band, which is being held in position beneath the sheaf by the band-carrier. When the mechanism has dropped to its lowest position, the rollers n^{15} on the hands will drop off the ends of the inclined guide-plates n^{23} , and the arms and fingers will snap together and seize the band. In order to position the band and guide the fingers, the lower ends of arms n^{13} are preferably branched, as shown, the branches n^{27} thereof entering slots n^{28} in the tubular fingers, so as to steady them, it being apparent also that the said branched ends will strike the band as it descends and insure its being in proper position to be seized by the fingers. As the frames n^{22} return to their normal position the inclined plates n^{23} ride down the other side of rollers n^{15} , tilting to the position shown in dotted lines, Fig. 68, to allow the parts to come to their normal relative positions, as shown in Fig. 74.

From the foregoing it will be seen that the band-tying mechanism will descend, straddle the formed and compressed sheaf, and grasp the twisted band which has been laid beneath the sheaf by the band-carrier, the operation of the respective parts being so timed relative to the movements of the other mechanisms as to bring them into coöperation therewith at the desired moment.

Assuming that the band-grasping fingers have seized the ends of the twisted band just inside of the band-grasping jaws of the trav-

eling band-carrier, hereinbefore described, the shaft N^5 and rack N^6 will begin to rise, pulling the twisted band out of the carrier-jaws and laying it about the sheaf as the arms n^{13} close as they travel upwardly in the grooved guideways N^3 . This will bring the band-grasping fingers, arms, and connected devices from their lower position (shown in full lines in Fig. 67) to their upper positions, (shown in dotted lines in the same figure,) with the cross-rods n^4 lying between locking-lugs n^{79} on the rotatable plate N^2 (see Figs. 76, 77, and 79) and with the upper guiding-arm n^5 supported by spring-fingers n^{82} , said fingers having inclined tips against which the arm n^5 strikes as the rack N^6 rises, (see Figs. 80 to 85, inclusive,) said fingers being normally held in their outer position by a spring n^{29} , a cam-plate n^{30} , engaging pins n^{31} on the fingers, serving to throw the fingers back and release the rack at a predetermined moment, said cam-plate being actuated by a lever n^{32} , which is struck by an arm n^{33} on the shaft N^9 to move the spring-fingers and automatically release the rising and falling tying mechanism at the proper time.

When the band-tying mechanism has been raised to its uppermost position, with its cross-rods locked to the rotatable plate and the spring-fingers n^{82} supporting the rack in the manner just described, the gear n^{33} on one side of the segment N^8 , hereinbefore referred to, will have advanced to a point where it will engage a pinion n^{34} , mounted in a hanger on a cross-bar n^{35} , supported by the fixed plate N , said pinion being splined to the shaft N^5 , so as to permit said shaft to slide freely therethrough in the rising and falling movements of the band-tying mechanism, but which will impart rotation to said shaft and its suspended parts when the pinion is engaged by the gear n^{33} as the segment N^8 is advanced by the rotation of shaft N^9 , which, as above described, has a driving connection with the power-shaft X through the chain n^{11} . As the segment N^8 comes over, an unlocking-bow n^{43} strikes a spring-closed locking-pawl n^{44} , which is pivoted to the plate N , and drops into a hole in the rotatable plate N^2 (see Figs. 76 and 77) to lock the two plates together during the rising and falling movements of the band-tying mechanism. This pawl n^{44} being thrown out just before the segment N^8 engages the pinion n^{34} and being held in releasing position by the bow n^{43} , the shaft N^5 and supported parts will be rotated by the pinion n^{34} , splined, as stated, to said shaft, with the result that the entire mechanism, comprising the sheaf-straddling arm, the band-hands, and the band-grasping fingers, between which fingers the band is tightly held, will be rotated. By this action the ends of the twisted band will be twisted together above the sheaf to form the tie, the beginning of this operation being shown in Fig. 67, in which figure the parts are shown

as having made the first half-turn of the tying twist, the completed twist being shown in Figs. 92 and 93. As this tying twist is taking place the sheaf is slowly lowered by the dropping of the sheaf-cradle under the action of the cams k^{14} k^{19} , which move the tilting beams supporting the two halves of the cradle, this lowering action having a double object—first, to prevent kinking of the tying twist, thus insuring a straight-twisted band end for the tucking devices to operate on, and, second, to give clearance for the tucker-carriage to travel forward on its supporting-tracks over the sheaf to seize and tuck the now tied band.

The tucking mechanism will now be described.

The band-tucker.—Mounted on suitable grooved tracks O , supported by standards O' , rising from the floor-beams of the harvester-frame, (see Figs. 4, 11, 12, 14, and 19,) is the carriage on which the tucker mechanism is mounted, said carriage comprising a substantially rectangular frame O^2 , Figs. 86 and 87, provided with supporting-rollers o , Figs. 86, to 88, inclusive, which travel in the grooved supporting-tracks O . Said frame O^2 has at one side a rack o' , which is engaged by a gear-segment o^2 on the shaft O^3 , (see Figs. 4, 11, 12, and 19,) said shaft being rotated to advance the tucker-carriage by means of a segment-gear o^3 on the power-shaft X , (see Figs. 1, 4, and 17,) which meshes with an idle gear o^4 , which latter meshes with and rotates a gear o^5 on the shaft O^3 . The reverse movement of shaft O^3 and tucker-carriage is effected by a segment-gear o^6 on the end of the shaft O^3 , (see Figs. 1, 4, and 17,) which is operated at the proper moment to return the tucker-carriage by means of a gear-segment o^7 on the power-shaft X . On the under side of the tucker-carriage is an upturned shoe o^8 , which rides over the sheaf as the tucker-carriage advances and prevents any entanglement of the tucker parts with the sheaf, said shoe having the vertical projections o^9 , which span the tucker-head shaft, presently to be described. Said tucker is also provided with two fixed guides o^{10} and o^{11} , (see Figs. 86 to 93, inclusive,) which direct the band to the tucker-head as the tucker-carriage advances to tucking position, the guide o^{11} being preferably adjustably mounted on a supporting-rod o^{12} , fixed to the carriage, as clearly shown in Figs. 86, 87, 88, and 89. In order to bring the band snugly home in proper position for the tucker-head to make the tuck and to support it in vertical position for the action of the tucking-blade, the pivoted band directing and supporting fingers o^{13} o^{14} are provided, both being carried by the pivoted gear-plate o^{15} , the finger o^{13} bringing the band snugly in front of the tucker-head and supporting it at that point while the offset-finger o^{14} serves to support said band at a point below and keep it vertical, all as will appear from the action of

the parts as shown in Figs. 86, 87, 88, and 89. The toothed plate σ^{15} , with its fingers σ^{13} σ^{14} is swung on its pivot by means of a rack σ^{16} at the end of a rod σ^{17} , connected to the end of a 5 rocking lever σ^{18} , pivoted on the carriage-frame, said lever having a toe σ^{19} , which engages a roller-stop σ^{20} (see Figs. 4, 12, and 14) in proximity to one of the tracks on which the carriage travels, said roller riding up the inclined toe σ^{19} , so as to give a thrust to the rack σ^{16} , tilt the pivoted plate σ^{15} , and hold it with its band-controlling fingers in the closed position shown in Fig. 87 until the carriage makes its return movement, when the lever σ^{18} 15 will be returned to its normal position by an adjustable weight σ^{21} on an arm of the lever, thus withdrawing the rack and swinging gear-plate σ^{15} and its fingers to starting position.

When the tucker-carriage has been advanced 20 and the band caught and brought home by the band directing and supporting fingers, the tucker-head is operated to make the tuck. The tucker-head O^4 comprises a head-block which is mounted on a shaft O^5 , journaled in 25 suitable bearings on the carriage. Said head-block is secured upon the shaft O^5 by means of the binding-screw σ^{50} (see Figs. 90, 91, 94, and 95) or other suitable securing means, so that the tucker-head O^4 may be readily detached from the shaft O^5 or adjusted longitudinally or axially thereon to bring the tucker-head O^4 to its proper position of adjustment. The tucker-head O^4 is provided with an extended portion σ^{220} , (see Fig. 94,) which forms 30 the immediate bearing or support upon which is mounted the thin curved band-tucking blade σ^{22} , having band-piercing teeth at its end, the said blade having a slot σ^{221} in its rear end, through which slot passes a clamping screw-bolt σ^{222} . It will be apparent, therefore, that 35 the blade σ^{22} may be adjusted lengthwise upon the tucker-head O^4 , so that a nice adjustment of the tucker may be made. Axial adjustment is provided to regulate the length of the tuck and interchangeability of blades of different lengths or removal if worn or broken is readily secured, said tucker-head being normally held in the position shown in Figs. 86 and 88 by a torsional spring σ^{23} , which is secured 40 to a collar σ^{24} on the shaft O^5 at one end, the other end of said spring being connected with an adjustable worm-wheel σ^{25} on the carriage-frame, a worm σ^{26} being provided, by means of which the worm-wheel σ^{25} may be rotated and the tension of spring σ^{23} varied. At 45 the rear end of the tucker-shaft O^5 is a segment of a gear-wheel O^6 , which is intermittently engaged by a segmental rack σ^{27} (see Fig. 19) on the main driving-shaft X, so as to 50 rotate the shaft O^5 and throw the tucker-head O^4 with its tucking-blade σ^{22} from the position shown in Figs. 90 and 91 to the position shown in Fig. 93, Fig. 92 representing the head about midway of its travel. As the tucker-head is 55 rocked over it strikes the band, which is held

vertically in its path, as hereinbefore set forth, the teeth on the end of the blade O^{22} biting into the band, and folds it over a spring-finger σ^{28} , carried by a swinging plate σ^{29} , pivoted to the tucker-carriage, said swinging plate 70 and folding-finger being connected by a link σ^{30} with an operating-lever σ^{31} , pivoted to the carriage-frame. (See Figs. 86 and 87.) Said lever σ^{31} , as the tucker-carriage advances, strikes a stop σ^{52} (see Figs. 4, 12, and 14) on 75 the carriage-supporting tracks, throwing said lever from the position shown in Fig. 86 to the position shown in Fig. 87, thus swinging the plate σ^{29} and the folding-finger carried thereby around so as to bring the finger directly in front of the band and below the path of the tucker-blade, as clearly shown in Figs. 87, 91, 92, and 93, inclusive, a spring σ^{33} normally holding the lever σ^{31} and its connected parts in the position shown in Fig. 86. The 80 support afforded the band by the finger σ^{28} enables the tucker-blade to form a loop or fold in the band, (see Fig. 92,) and as the tucker continues its movement the finger σ^{28} , which is pivoted to the plate σ^{29} and normally held 85 in the position shown by the spring σ^{34} , secured to an adjustable spool σ^{35} on the plate σ^{29} , said spring at its other end engaging a pin σ^{36} on the finger, yields downwardly, allowing the band to slip off and permitting the 90 tucking-blade to carry the twisted and tied band ends beneath the band to complete the tuck, as clearly shown in Fig. 93. The said tucking-blade σ^{22} passes beneath the band and also beneath the sheaf-compressor yoke M^3 95 between the teeth m^{31} thereon, which teeth form stops for the band, preventing the tucker-blade forcing the band proper out of place should it happen to catch on the band in making the tuck, the end of the compressor-arm being forked to give a clearance for the end of the tucking-blade σ^{22} as it moves to the extreme position. When the tucker has made its extreme forward movement, the segmental 100 actuating-rack σ^{27} will pass out of engagement with the gear-segment O^6 , and the torsional spring σ^{23} will immediately return the shaft O^5 and tucker-head to its starting position. 105

In order that all danger of pulling out the tucked band as the tucker-blade is withdrawn may be eliminated, a tuck-holding prong σ^{37} is provided, said prong being carried by a lever σ^{38} , pivoted to the tucker-carriage, (see Figs. 86 to 93, inclusive,) and being controlled by a cam O^7 (see Figs. 97 and 98) on the shaft O^5 , which is engaged by a spring-pressed pivoted finger σ^{39} , carried by the lever σ^{38} . A spring σ^{40} , fixed to the carriage-frame and connected by link σ^{41} to the lever σ^{38} , normally tends to throw the lever σ^{38} and the 115 tuck-holding prong σ^{37} downwardly to pierce the tuck, as shown in Figs. 88 and 89, the cam O^7 being so timed that the roller σ^{42} on the finger σ^{39} will ride along the circumferential edge σ^{43} of the cam and hold the lever 120

125

130

and tuck-holding prong up against the stress of spring σ^{10} until the tucking devices have completed the tucking operation. At this moment the roller σ^{42} will drop off the cam-point σ^{44} , and the lever σ^{38} will be thrown down by its spring, the prong σ^{37} piercing the tuck (see Fig. 93) and holding it during the withdrawal of the tucking-blade. The finger σ^{39} will ride back along the radial cam projection σ^{45} on the face of the cam to the circumferential cam-surface σ^{43} ready for the lifting of the lever and disengagement of the tuck-holding finger from the tucked band after the withdrawal of the tucking-blade. The tucking operation having been completed, the tucker-carriage will make its return movement, the compressor M^2 will be released and thrown back by the torsional spring, and the bound and tucked sheaf will lie in the sheaf-cradle ready for delivery. The sheaf will then be thrown from the machine by means which will now be described.

The sheaf-delivering mechanism.—The sheaf-cradle, as has been stated hereinbefore, is made up of two parts, each part comprising substantially U-shaped cradle-arms k^6 k^6 k^{16} , (see Figs. 1, 2, 3, 12, 14, 16, 19, 33, 34, and 35,) the pairs of arms being mounted on rocking shafts or rods k^7 k^{17} , respectively, fixed rods k^{20} k^{11} supporting the arms k^6 k^{16} , respectively, on the other side of their centers. The said shaft k^7 has at one end an arm P , with which a pull-rod P' is adjustably connected, said pull-rod P' sliding through a keeper p at the end of swinging arm P^3 , carried by the shaft O^3 , (see Figs. 33, 34, and 36 to 39, inclusive,) which shaft, as has been shown, carries the segment which moves the tucker-carriage forward and back. The said arm P^3 has a spring-latch p^2 provided with an operating-lever p^3 , and as the arm P^3 swings with the shaft O^3 as the tucker advances to tucking position the keeper p slides idly along the pull-rod P' , the latch p^2 riding over an inclined projection p^{60} on the pull-rod without disturbing the latter or the sheaf-cradle. As said arm P^3 swings it is locked by means of a locking-lever p^5 , which snaps behind a projection p^6 on the arm P^3 and holds the arm, the shaft O^3 , and segment σ^2 , which moves the tucker-carriage, locked in position, thus holding the tucker locked in its operative tucking position. At the moment when the tucker has completed its tucking operation a cam projection p^7 on a disk p^{70} , carried by the power-shaft X , strikes a roller p^8 at the end of lever p^5 and throws said lever out of locking engagement with arm P^3 , thus releasing the locked parts for the return movement. As shaft O^3 makes its reverse rotation the arm P^3 swings back, and just as the tucker retreats and clears the sheaf the latch p^2 strikes the projection p^{60} on the pull-rod P' . The continued movement of the arm P^3 exerts a pull on rod P' , rocking the shaft k^7 and tilt-

ing the cradle-arms k^6 k^6 until the latch p^2 is disengaged from the projection p^{60} by a curved projection p^4 on the frame striking the latch-lever p^3 , whereupon the arm P^3 will slide idly on the pull-rod P' . The said rock-shaft k^7 70 has an arm p^9 fixed thereto, (see Figs. 33 and 34,) which is connected by a rod p^{10} with a rocking bar p^{11} , pivoted in lugs p^{12} on the tilting cradle-beams k^{13} k^{18} , a second rod p^{13} connecting said rocking bar p^{11} with an arm p^{31} on the rock-shaft k^{17} , which supports the arms k^{16} of the other half of the tilting cradle. By these connections a simultaneous rocking movement is imparted to both halves of the cradle when the swinging arm P^3 pulls back on the 80 rod P' . This will tip the cradle up into delivering position, (see Fig. 16,) and the sheaf will be thrown out of the cradle by the action of the arms p^{14} , (see Figs. 16 and 33,) which normally lie beneath the sheaf between the 85 arms of the sheaf-cradle. Said sheaf-throwing arms p^{14} are mounted on small crank-shafts p^{15} , suitably journaled in supporting-brackets p^{16} and connected by links p^{17} with the ends of the arms p^9 p^{31} on the rock-shafts k^7 k^{17} , respectively. It will be clear, however, that as the cradle is tipped the sheaf-ejecting arms p^{14} will be thrown to the position shown in Fig. 16, and thus lift and throw the sheaf out of the tilted cradle. The ejected sheaf falls 95 upon the skid-rods p^{20} at the delivery end of the harvester and slides to the ground ready for the stackers.

It is believed that the operation and coöperation of the several mechanisms which go to make up the binder will be clear from the foregoing description, and a rehearsal of the action of the machine is deemed not necessary.

While I have shown and described a particular construction, I wish it to be understood that this is merely an illustrative embodiment of my invention and that any mere mechanical changes in the construction are within the scope of my invention, and I do not, therefore, limit myself to anything shown and described, except so far as I am limited by the terms of the appended claims.

Having thus described my invention, I claim and desire to secure by Letters Patent—

1. In a self-binder harvester, the combination with suitable grain-cutting and sheaf-forming apparatus, of a main conveyer to carry the grain which is to form the sheaf to the sheaf-forming devices, an independent auxiliary conveyer which receives the grain 115 which is to form the band-straw direct from the cutting apparatus, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

2. In a self-binder harvester, the combination with suitable grain-cutting and sheaf-

forming apparatus, of a conveyer to carry the cut grain to the sheaf-forming devices, an independent conveyer traveling parallel to the direction of travel of the machine which receives the band-straw direct from the cutting apparatus, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

3. In a self-binder harvester, the combination with suitable grain-cutting and sheaf-forming apparatus; of a conveyer to carry the cut grain to the sheaf-forming devices, a second conveyer traveling at right angles to the line of travel of the said first-named conveyer and parallel to the direction of travel of the machine which second conveyer receives the band-straw direct from the cutting apparatus, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

4. In a self-binder harvester, the combination with suitable grain-cutting and sheaf-forming apparatus, of band forming and tying instrumentalities comprising a conveyer to receive the band-straw, means for separating the standing grain which is to form the band-straw from the bulk which forms the sheaf and directing it to the cutting apparatus and the said straw-conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

5. In a self-binder harvester, the combination with suitable grain-cutting and sheaf-forming apparatus, of a conveyer to receive the bulk or sheaf portion of the cut grain and carry it to the sheaf-forming devices, a second conveyer to receive a portion of the cut grain to form the band-straw, means for separating the standing grain into sheaf and band portions and directing each portion to the cutting apparatus and the proper conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

6. In a self-binder harvester, the combination with suitable grain-cutting and sheaf-forming apparatus, of a conveyer to receive the bulk or sheaf portion of the cut grain and carry it to the sheaf-forming devices, a second

conveyer to receive a portion of the cut grain to form the band-straw, means for separating the standing grain into sheaf and band portions and directing each portion to the cutting apparatus and the proper conveyer, means for adjusting said separating means so as to vary the amount of grain directed to each conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

7. In a self-binder harvester, the combination with suitable grain-cutting and sheaf-forming apparatus, of a conveyer for the bulk or sheaf portion of the cut grain traveling at right angles to the line of travel of the machine, a second conveyer traveling at right angles to the line of travel of the first-named conveyer and parallel to the line of travel of the machine to receive a portion of the cut grain as it falls before the cutting apparatus to form the band-straw, means for separating the standing grain into sheaf and band portions and directing each portion to the cutting apparatus and the proper conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

8. In a self-binder harvester, the combination with suitable grain-cutting and sheaf-forming apparatus, of a conveyer upon which the bulk or sheaf portion of the cut grain falls, an independent auxiliary conveyer upon which the band portion of the cut grain falls, and a single cutting apparatus spanning and delivering to both of said conveyers.

9. In a self-binder harvester, the combination with suitable sheaf-forming apparatus, of a conveyer for the bulk or sheaf portion of the grain, an independent conveyer for the band portion of the grain, means for separating the standing grain into sheaf and band portions and directing each portion toward the proper conveyer, and a single cutting apparatus spanning and delivering to both of said conveyers.

10. In a self-binder harvester, the combination with suitable grain-cutting and sheaf-forming apparatus, of band forming and tying instrumentalities comprising a conveyer to receive the band-straw, means for directing the grain to said conveyer, means for adjusting said grain-directing means to vary the amount of grain fed to the conveyer, means for straightening the swamped or fallen grain for the said conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

shaped band, a band-carrier to deliver the twisted band to the sheaf, and means for tying and tucking the said band about the sheaf.

11. In a self-binder harvester, the combination with suitable cutting apparatus, of a band-straw conveyer, means for picking up and straightening swamped or fallen grain in advance of the cutting apparatus, so that when cut it may fall in straight orderly fashion upon said conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

12. In a self-binder harvester, the combination with a suitable cutting apparatus, of a band-straw conveyer traveling parallel to the line of travel of the machine, means for picking up and straightening swamped or fallen grain in advance of the cutting apparatus so that when cut it may fall in straight orderly fashion upon said band-straw conveyer, compressing devices to which said band-straw conveyer delivers to initially compact and shape the band, twisting mechanism to twist the compacted and shaped band, a band-carrier to deliver the twisted band to the sheaf, and means for tying and tucking the said band about the sheaf.

13. In a self-binder harvester, the combination with a suitable grain-cutting and sheaf-forming apparatus, of band forming and tying instrumentalities comprising a conveyer to receive the band-straw, means for directing the grain to said conveyer, means for adjusting said grain-directing means to vary the amount of grain fed to the conveyer, pick-up devices to straighten the grain for the said conveyer, compressing devices to initially compact and shape the band, twisting mechanism to twist the compacted and shaped band, a band-carrier to deliver the twisted band to the sheaf, and means for tying and tucking the said band about the sheaf.

14. In a self-binder harvester, the combination with suitable grain-cutting and sheaf-forming apparatus, of band forming and tying instrumentalities comprising a conveyer-belt to receive the band-straw, compressing-chains to initially compact and shape the band, twisting mechanism to twist the compacted and shaped band, a band-carrier to deliver the twisted band to the sheaf, and means for tying and tucking the said band about the sheaf.

15. In a self-binder harvester, the combination with suitable grain-cutting and sheaf-forming apparatus, of band forming and tying instrumentalities comprising a conveyer-belt to receive the band-straw, interlocking compressing-chains to initially compact and shape the band, twisting mechanism to twist the compacted and shaped band, a band-carrier to deliver the twisted band to the sheaf, and means

for tying and tucking the said band about the sheaf.

16. In a self-binder harvester, the combination with suitable grain-cutting and sheaf-forming apparatus, of band forming and tying instrumentalities comprising a conveyer-belt to receive the band-straw, interlocking compressing-chains to initially compact and shape the band, twisting mechanism to twist the compacted and shaped band, means for severing a band length from said twisted band, a band-carrier to deliver said severed band length to the sheaf, and means for tying and tucking the said band about the sheaf.

17. In a self-binder harvester, the combination with suitable grain-cutting and sheaf-forming apparatus, of band forming and tying instrumentalities comprising a conveyer-belt to receive the band-straw, interlocking compressing-chains to initially compact and shape the band, twisting mechanism to twist the compacted and shaped band, means for severing a band length from said twisted band, means for holding said severed length in twisted condition, a band-carrier to deliver said severed band length to the sheaf, and means for tying and tucking the said band about the sheaf.

18. In a self-binder harvester, the combination with suitable grain-cutting and sheaf-forming apparatus, of band forming and tying instrumentalities comprising a conveyer to receive the band-straw as it falls before the cutting apparatus, means for separating the uncut band-straw grain from the bulk and for directing the grain to the cutting apparatus and said conveyer, means for initially compacting and shaping said straw into a band, means for twisting said compacted and shaped band, means for severing a band length from said twisted band, means for delivering said severed band length to the sheaf, and means for tying and tucking the said band about the sheaf.

19. In a self-binder harvester, the combination with suitable grain-cutting and sheaf-forming apparatus, of band forming and tying instrumentalities comprising a conveyer-belt to receive the band-straw as it falls before the cutting apparatus, vertical separator-boards on either side of said conveyer-belt to direct the band-straw to said belt, means to receive the straw from said conveyer-belt and initially compact and shape the same into a band, means for twisting said compacted and shaped band, means for severing a twisted band length, means for delivering said severed and twisted length to the sheaf, and means for tying and tucking said band about the sheaf.

20. In a self-binder harvester, the combination with suitable grain-cutting and sheaf-forming apparatus, of band forming and tying instrumentalities comprising a conveyer-belt to receive the band-straw as it falls before the cutting apparatus, vertical separator-boards on either side of said conveyer-belt to direct

the band-straw to said belt, means for adjusting one of said boards to vary the amount of straw delivered to the conveyer-belt, means to receive the straw from said conveyer-belt 5 and initially compact and shape the same into a band, means for twisting said compacted and shaped band, means for severing a twisted band length, means for delivering said severed and twisted length to the sheaf, and 10 means for tying and tucking said band about the sheaf.

21. In a self-binder harvester, the combination with suitable grain-cutting and sheaf-forming apparatus, of band forming and tying instrumentalities comprising a conveyer-belt 15 to receive the band-straw as it falls before the cutting apparatus, vertical separator-boards on either side of said conveyer-belt to direct the band-straw to said belt, means for adjusting one of said boards to vary the amount of straw delivered to the conveyer-belt, pick-up chains carried by said boards to straighten the grain for delivery to the band-straw conveyer-belt, means to receive the straw from 20 said conveyer-belt and initially compact and shape the same into a band, means for twisting said compacted and shaped band, means for severing a twisted band length, means for delivering said severed and twisted length to 25 the sheaf, and means for tying and tucking said band about the sheaf.

22. In a self-binder harvester, the combination with suitable grain-cutting and sheaf-forming apparatus, of band forming and tying 35 instrumentalities comprising a conveyer-belt to receive the band-straw as it falls before the cutting apparatus, means for directing the band-straw to said conveyer-belt, means for straightening the band-straw for delivery to 40 said conveyer-belt, interlocking compressing-chains to initially compact and shape the straw into a band, means for twisting said compacted and shaped band, means for severing a band length from 45 said twisted band, means for delivering said severed band length to the sheaf, and means for tying and tucking said band about the sheaf.

23. In a self-binder harvester, the combination with suitable grain-cutting and sheaf-forming apparatus, of band forming and tying 50 instrumentalities comprising a conveyer-belt to receive the band-straw as it falls before the cutting apparatus, means for directing the band-straw to said conveyer-belt, means for straightening the band-straw for delivery to 55 said conveyer-belt, interlocking compressing-chains to initially compact and shape the straw into a band, one of said chains having guard-plates to cover the link-openings, means for 60 twisting said compacted and shaped band, means for severing a band length from said twisted band, means for delivering said severed length to the sheaf, and means for tying and tucking said band about the sheaf.

65 24. In a self-binder harvester, the combina-

tion with suitable grain-cutting and sheaf-forming apparatus, of band forming and tying instrumentalities comprising a conveyer-belt to receive the band-straw as it falls before the cutting apparatus, means for directing the 70 band-straw to said conveyer-belt, means for straightening the band-straw for delivery to said conveyer-belt, interlocking compressing-chains to initially compact and shape the straw into a band, means for deflecting the straw 75 away from the chain-link openings, means for twisting said compacted and shaped band, means for severing a band length from said twisted band, means for delivering said severed length to the sheaf, and means for tying 80 and tucking said band about the sheaf.

25. In a self-binder harvester, the combination with suitable grain-cutting and sheaf-forming apparatus, of band forming and tying instrumentalities comprising a conveyer-belt 85 to receive the band-straw as it falls before the cutting apparatus, means for directing the band-straw to said conveyer-belt, means for straightening the band-straw for delivery to said conveyer-belt, interlocking compressing- 90 chains to initially compact and shape the straw into a band, one of said chains having spring guard-plates to cover the link-openings, means for twisting said compacted and shaped band, means for severing a band length from 95 said twisted band, means for delivering said severed length to the sheaf, and means for tying and tucking said band about the sheaf.

26. In a self-binder harvester, the combination with suitable grain-cutting and sheaf-forming apparatus, of band forming and tying 100 instrumentalities comprising a conveyer-belt to receive the band-straw as it falls before the cutting apparatus, means for directing the band-straw to said conveyer-belt, 105 means for straightening the band-straw for delivery to said conveyer-belt, compressing-chains to initially compact and shape the straw into a band, said chains having links provided with lugs to embrace the links of the opposing 110 chain and interlock the chains, means for twisting said compacted and shaped band, means for severing a band length from said twisted band, means for delivering said severed length to the sheaf, and means for tying 115 and tucking said band about the sheaf.

27. In a self-binder harvester, the combination with suitable grain-cutting and sheaf-forming apparatus, of band forming and tying instrumentalities comprising a conveyer-belt 120 to receive the band-straw as it falls before the cutting apparatus, compressing-chains to initially compact and shape the straw into a band, a traveling twister-carriage, band-twisting devices carried thereby, means for 125 severing a twisted band length, means for delivering said twisted band length to the sheaf, and means for tying and tucking said band about the sheaf.

28. In a self-binder harvester, the combina- 130

tion with suitable grain-cutting and sheaf-forming apparatus, of band forming and tying instrumentalities comprising a conveyer-belt to receive the band-straw as it falls before the 5 cutting apparatus, compressing-chains to initially compact and shape the straw into a band, a traveling twister-carriage, rotary band-twisting devices carried thereby, means for rotating said band-twisting devices, means for 10 severing a twisted band length, means for delivering said twisted band length to the sheaf, and means for tying and tucking said band about the sheaf.

29. In a self-binder harvester, the combination 15 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, a traveling twister-carriage, means for moving 20 said carriage, band-grasping twister-jaws on said carriage, means for rotating said jaws, means for severing a twisted band length, 25 means for delivering said twisted band length to the sheaf, and means for tying and tucking said band about the sheaf.

30. In a self-binder harvester, the combination 30 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, 35 a traveling twister-carriage, means for moving said carriage, spring band-grasping twister-jaws on said carriage, means for opening said jaws, means for rotating said jaws, means for severing a twisted band length, 40 means for delivering said twisted band length to the sheaf, and means for tying and tucking said band about the sheaf.

31. In a self-binder harvester, the combination 45 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, 50 a traveling twister-carriage, means for moving said carriage, spring band-grasping twister-jaws on said carriage, means for automatically opening said jaws, means for rotating said jaws, means for severing a twisted 55 band length, means for delivering said twisted band length to the sheaf, and means for tying and tucking said band about the sheaf.

32. In a self-binder harvester, the combination 60 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, 65 a traveling twister-carriage, means for mov-

ing said carriage, band-grasping twister-jaws on said carriage, means for automatically effecting the closing of said jaws at a predetermined position of said twister-carriage, means for rotating said jaws, means for automatically 70 opening said jaws at a predetermined position of said twister-carriage, means for severing a twisted band length, means for delivering said twisted band length to the sheaf, and means for tying and tucking said band about 75 the sheaf.

33. In a self-binder harvester, the combination 80 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, a traveling twister-carriage, means for moving 85 said carriage, spring-closed band-grasping twister-jaws on said carriage, means for automatically effecting the closing of said spring-jaws at a predetermined position of said twister-carriage, means for rotating said jaws, means for automatically opening said spring-jaws at a predetermined position of said 90 twister-carriage, means for severing a twisted band length, means for delivering said twisted band length to the sheaf, and means for tying and tucking said band about the sheaf. 95

34. In a self-binder harvester, the combination 100 with suitable grain-cutting and sheaf-forming apparatus, of band forming and tying instrumentalities comprising a conveyer-belt to receive the band-straw as it falls before the cutting apparatus, compressing-chains to initially compact and shape the straw into a band, a traveling twister-carriage, means for moving 105 said carriage, spring-closed band-grasping twister-jaws on said carriage, means for automatically effecting the closing of said spring-jaws at a predetermined position of said twister-carriage, means for rotating said jaws during the outward travel of said carriage, means for automatically opening said spring-jaws at a predetermined position of said twister-carriage, means for severing a twisted band length, means for delivering said twisted band length to the sheaf, and means for 110 tying and tucking said band about the sheaf. 115

35. In a self-binder harvester, the combination 120 with suitable grain-cutting and sheaf-forming apparatus, of band forming and tying instrumentalities comprising a band-straw conveyer, means for initially shaping and compressing the straw into a band, a traveling twister-carriage provided with band-twisting devices, means for severing a band length from the twisted band, means for delivering a severed band length in twisted condition to 125 the sheaf, and means for tying and tucking said band about the sheaf.

36. In a self-binder harvester, the combination 130 with suitable grain-cutting and sheaf-forming apparatus, of band forming and tying

instrumentalities comprising a conveyer which receives the band-straw direct from the cutting apparatus, instrumentalities to initially compact and shape the band, a twister-spout 5 composed of yielding pivoted sections to receive the band from said band-shaping instrumentalities, a band-twister to twist the shaped band as it issues from said twister-spout, a band-severing knife to sever a band length 10 from the twisted band, a band-carrier to deliver said severed length to the sheaf, and means for tying and tucking said band about the sheaf.

37. In a self-binder harvester, the combination 15 with suitable grain-cutting and sheaf-forming apparatus, of band forming and tying instrumentalities comprising a conveyer which receives the band-straw direct from the cutting apparatus, instrumentalities to initially compact and shape the band, a twister-spout composed of pivoted spring-closed sections to receive the band from said band-shaping instrumentalities, a band-twister to twist the shaped band as it issues from said twister-spout, a band-severing knife to sever a band length 20 from the twisted band, a band-carrier to deliver said severed length to the sheaf, and means for tying and tucking said band about the sheaf.

38. In a self-binder harvester, the combination 25 with suitable grain-cutting and sheaf-forming apparatus, of band forming and tying instrumentalities comprising a conveyer which receives the band-straw direct from the cutting apparatus, instrumentalities to initially compact and shape the band, a twister-spout composed of yielding pivoted sections to receive the band from said band-shaping instrumentalities, a band-twister to twist the shaped 30 band as it issues from said twister-spout, a spring-actuated band-severing knife to sever a band length from the twisted band, a band-carrier to deliver said severed length to the sheaf, and means for tying and tucking said 35 band about the sheaf.

39. In a self-binder harvester, the combination 40 with suitable grain-cutting and sheaf-forming apparatus, of band forming and tying instrumentalities comprising a conveyer which receives the band-straw direct from the cutting apparatus, instrumentalities to initially compact and shape the band, a twister-spout composed of yielding pivoted sections to receive the band from said band-shaping instrumentalities, a band-twister to twist the shaped 45 band as it issues from said twister-spout, a spring-actuated band-severing knife to sever a band length from the twisted band, means for retracting said spring-actuated knife, a band-carrier to deliver said severed length to the sheaf, and means for tying and tucking said band about the sheaf.

40. In a self-binder harvester, the combination 50 with suitable grain-cutting and sheaf-forming apparatus, of band forming and tying

instrumentalities comprising a conveyer to receive the band-straw as it falls before the cutting apparatus, instrumentalities to initially compact and shape the band, band-twisting devices to twist the shaped and compacted 70 band, means for severing a band length from the twisted band, a traveling band-carrier to deliver the severed band length to the sheaf, band-grasping jaws on said band-carrier to seize said twisted and severed band at either 75 end, and means for tying and tucking said band about the sheaf.

41. In a self-binder harvester, the combination 80 with suitable grain-cutting and sheaf-forming apparatus, of band forming and tying instrumentalities comprising a conveyer to receive the band-straw as it falls before the cutting apparatus, instrumentalities to initially compact and shape the band, band-twisting devices to twist the shaped and compacted 85 band, means for severing a band length from the twisted band, a traveling band-carrier to deliver the severed band length to the sheaf, band-grasping jaws on said band-carrier to seize said twisted and severed band at either 90 end, means for automatically opening said jaws at a predetermined point in the travel of said band-carrier, and means for tying and tucking said band about the sheaf.

42. In a self-binder harvester, the combination 95 with suitable grain-cutting and sheaf-forming apparatus, of band forming and tying instrumentalities comprising a conveyer to receive the band-straw as it falls before the cutting apparatus, instrumentalities to initially 100 compact and shape the band, band-twisting devices to twist the shaped and compacted band, means for severing a band length from the twisted band, a traveling band-carrier to deliver the severed band length to the sheaf, band-grasping jaws on said band-carrier to seize said twisted and severed band at either 105 end, means for automatically opening said jaws at a predetermined point in the travel of said band-carrier, means for supporting the 110 band intermediate its ends, and means for tying and tucking said band about the sheaf.

43. In a self-binder harvester, the combination 115 with suitable grain-cutting and sheaf-forming apparatus, of band forming and tying instrumentalities comprising a conveyer to receive the band-straw as it falls before the cutting apparatus, instrumentalities to initially compact and shape the band, band-twisting devices to twist the shaped and compacted 120 band, a reciprocating band-severing knife for severing a band length from the twisted band, means for actuating said knife, a traveling band-carrier to deliver the severed band length to the sheaf, band-grasping jaws on said band-carrier to seize said twisted and severed band at either 125 end, and means for tying and tucking said band about the sheaf.

44. In a self-binder harvester, the combination 130 with suitable grain-cutting and sheaf-

- forming apparatus, of band forming and tying instrumentalities comprising a conveyer to receive the band-straw as it falls before the cutting apparatus, instrumentalities to initially 5 compact and shape the band, band-twisting devices to twist the shaped and compacted band, a spring-actuated reciprocating band-severing knife for severing a band length from the twisted band, means for releasing said 10 knife, a traveling band-carrier to deliver the severed band length to the sheaf, band-grasping jaws on said band-carrier to seize said twisted and severed band at either end, and means for tying and tucking said band about the sheaf.
45. In a self-binder harvester, the combination with suitable grain-cutting and sheaf-forming apparatus, of band forming and tying instrumentalities comprising a conveyer to receive the band-straw as it falls before the cutting apparatus, instrumentalities to initially 20 compact and shape the band, band-twisting devices to twist the shaped and compacted band, a spring-actuated reciprocating knife-carrier, a band-severing blade pivoted on said carrier, means for releasing said knife-carrier and knife to sever a band length from the twisted band, a traveling band-carrier to deliver the severed band length to the sheaf, 25 band-grasping jaws on said band-carrier to seize said twisted and severed band at either end, and means for tying and tucking said band about the sheaf.
46. In a self-binder harvester, the combination with suitable grain-cutting and sheaf-forming apparatus, of band forming and tying instrumentalities comprising a conveyer to receive the band-straw as it falls before the cutting apparatus, instrumentalities to initially 30 compact and shape the band, band-twisting devices to twist the shaped and compacted band, a spring-actuated reciprocating knife-carrier, a band-severing knife pivoted on said carrier, means for releasing said knife-carrier and knife to sever a band length from the twisted band, means for depressing said pivoted knife on the return movement of the knife-carrier, a traveling band-carrier to deliver the severed band length to the sheaf, 35 band-grasping jaws on said band-carrier to seize said twisted and severed band at either end, and means for tying and tucking said band about the sheaf.
47. In a self-binder harvester, the combination with suitable grain-cutting and sheaf-forming apparatus, of band forming and tying instrumentalities comprising a conveyer to receive the band-straw as it falls before the cutting apparatus, instrumentalities to initially 40 compact and shape the band, band-twisting devices to twist the shaped and compacted band, a spring-actuated reciprocating knife-carrier, a spring-supported band-severing knife pivoted on said carrier, means for releasing said knife-carrier and knife to sever a band length from the twisted band, means for depressing said pivoted knife on the return movement of the knife-carrier, a traveling band-carrier to deliver the severed band length to the sheaf, 45 band-grasping jaws on said band-carrier to seize said twisted and severed band at either end, and means for tying and tucking said band about the sheaf.
48. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 50 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

49. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 55 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

50. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 60 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

51. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 65 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

52. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 70 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

53. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 75 means for severing a band length from said twisted band, means for delivering and holding said twisted and severed band length in tying position relative to the sheaf, rising and falling band-tying devices to seize said band on either side of the sheaf, means for rotating said devices to give the band ends a tying twist about the sheaf, and means for tucking the twisted band about the sheaf.

means for severing a band length from said twisted band, means for delivering and holding said twisted and severed band length in tying position relative to the sheaf, rising and falling band-tying hands having spring-actuated fingers to seize said band on either side of the sheaf, means for rotating said hands to give the band ends a tying twist above the sheaf, and means for tucking the twisted band ends beneath the band.

52. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering and holding said twisted and severed band length in tying position relative to the sheaf, rising and falling band-tying hands having spring-actuated interlocking fingers to seize said band on either side of the sheaf, means for rotating said hands to give the band ends a tying twist above the sheaf, and means for tucking the twisted band ends beneath the band.

53. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering said twisted and severed band length to the sheaf, sheaf-straddling arms mounted above the sheaf, means for raising and lowering said sheaf-straddling arms, means for opening and closing said sheaf-straddling arms, band-tying hands carried by said sheaf-straddling arms to seize said band on either side of the sheaf, means for rotating said sheaf-straddling arms to give the band ends a tying twist above the sheaf, and means for tucking the twisted band ends beneath the band.

54. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering said twisted and severed band length to the sheaf, pivoted sheaf-straddling arms mounted above the sheaf, means for raising and lowering said sheaf-straddling arms, means for opening and closing said pivoted sheaf-straddling arms, band-tying hands carried by said sheaf-straddling arms to seize said band on either side of the sheaf, means for rotating said sheaf-straddling arms to give the band ends a tying twist above the

above the sheaf, and means for tucking the twisted band ends beneath the band.

55. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering said twisted and severed band length to the sheaf, pivoted sheaf-straddling arms mounted above the sheaf, means for raising and lowering said sheaf-straddling arms, means for opening and closing said pivoted sheaf-straddling arms, pivoted band-tying hands carried by said sheaf-straddling arms to seize said band on either side of the sheaf, means for rotating said sheaf-straddling arms to give the band ends a tying twist above the sheaf, and means for tucking the twisted band ends beneath the band.

56. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering said twisted and severed band length to the sheaf, pivoted sheaf-straddling arms mounted above the sheaf, means for raising and lowering said sheaf-straddling arms, means for opening and closing said pivoted sheaf-straddling arms, pivoted band-tying hands carried by said sheaf-straddling arms, interlocking band-grasping fingers on said hands to seize said band on either side of the sheaf, means for rotating said sheaf-straddling arms to give the band ends a tying twist above the sheaf, and means for tucking the twisted ends beneath the band.

57. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, means for severing a band length from said twisted band, means for delivering said twisted and severed band length to the sheaf, pivoted sheaf-straddling arms mounted above the sheaf, means for raising and lowering said sheaf-straddling arms, means for opening and closing said pivoted sheaf-straddling arms, pivoted band-tying hands carried by said sheaf-straddling arms, spring-actuated interlocking fingers on said pivoted hands to seize said band on either side of the sheaf, means for rotating said sheaf-straddling arms to give the band ends a tying twist above the

sheaf, and means for tucking the twisted band ends beneath the band.

58. In a self-binder harvester, the combination with suitable grain-cutting and sheaf-forming apparatus, of band forming and tying instrumentalities comprising a conveyer for the band-straw, compressing devices to initially compact and shape the band, band-twisting mechanism to twist said compacted band, 10 means for severing a band length from said twisted band, means for delivering said twisted and severed band length to the sheaf, pivoted sheaf-straddling arms mounted above the sheaf, means for raising and lowering said 15 sheaf-straddling arms, means for opening and closing said pivoted sheaf-straddling arms, pivoted band-tying hands carried by said sheaf-straddling arms, spring-actuated interlocking fingers on said hands to seize said band 20 on either side of the sheaf, means for locking said sheaf-straddling arms in their raised positions, means for rotating said locked sheaf-straddling arms to give the band ends a tying twist above the sheaf, and means for tucking 25 the twisted band ends beneath the band.
59. In a self-binder harvester, the combination with suitable grain-cutting and sheaf-forming apparatus, of band forming and tying instrumentalities comprising a conveyer for 30 the band-straw, means for initially compacting and shaping the band, twister mechanism for twisting the compacted and shaped band, means for severing a band length from the 35 twisted band, a band-carrier to deliver the twisted band length to the sheaf, pivoted sheaf-straddling arms mounted above the sheaf, means for raising and lowering said arms, means for automatically opening said arms as they lower and closing said arms as they rise, 40 band-grasping hands pivoted on said sheaf-straddling arms, means for automatically opening said hands as the sheaf-straddling arms descend, means for closing said hands upon the band when they reach their lower- 45 most position, means for rotating said sheaf-straddling arms as they rise above the sheaf to give a tying twist to the band ends, and means for tucking said twisted band ends beneath the band.
- 50 60. In a self-binder harvester, the combination with suitable grain-cutting and sheaf-forming apparatus, of band forming and tying instrumentalities comprising a conveyer for the band-straw, means for initially compact- 55 ing and shaping the band, twister mechanism for twisting the compacted and shaped band, means for severing a band length from the twisted band, a band-carrier to deliver the twisted band length to the sheaf, pivoted 60 sheaf-straddling arms mounted above the sheaf, means for raising and lowering said arms, means for automatically opening said arms as they rise, band-grasping hands pivoted on said 65 sheaf-straddling arms, means for automatic-

ally opening said hands as the sheaf-straddling arms descend, means for closing said hands upon the band when they reach their lowermost position, means for directing the band to said hands, means for rotating said 70 sheaf-straddling arms as they rise above the sheaf to give a tying twist to the band ends, and means for tucking said twisted band ends beneath the band.

61. In a self-binder harvester, the combination with suitable grain-cutting and sheaf-forming apparatus, of band forming and tying instrumentalities comprising a conveyer for the band-straw, means for initially compacting and shaping the band, twister mechanism 80 for twisting the compacted and shaped band, means for severing a band length from the twisted band, a band-carrier to deliver the twisted band length to the sheaf, pivoted sheaf-straddling arms mounted above the 85 sheaf, means for raising and lowering said arms, means for automatically opening said arms as they lower and closing said arms as they rise, band-grasping hands pivoted on said sheaf-straddling arms, means for holding 90 said hands normally closed, means for automatically opening said hands as the sheaf-straddling arms descend, means for releasing said hands when they reach their lowermost position, means for directing the band to said 95 hands, means for rotating said sheaf-straddling arms as they rise above the sheaf to give a tying twist to the band ends, and means for tucking said twisted ends beneath the band.

62. In a self-binder harvester, the combination with suitable grain-cutting and sheaf-forming apparatus, of band forming and tying instrumentalities comprising a conveyer for the band-straw, means for initially compact- 105 ing and shaping the band, twister mechanism for twisting the compacted and shaped band, means for severing a band length from the twisted band, a band-carrier to deliver the twisted band length to the sheaf, pivoted sheaf- 110 straddling arms mounted above the sheaf, means for raising and lowering said arms, means for automatically opening said arms as they lower and closing said arms as they rise, band-grasping hands pivoted on said sheaf- 115 straddling arms, springs for holding said hands normally closed, means for automatically opening said hands against the stress of said springs as the sheaf-straddling arms descend, means for releasing said hands when they reach their 120 lowermost position, means for directing the band to said hands, means for rotating said sheaf-straddling arms as they rise above the sheaf to give a tying twist to the band ends, and means for tucking said twisted band ends 125 beneath the band.

63. In a self-binder harvester, the combination with suitable grain-cutting and sheaf-forming apparatus, of band forming and tying instrumentalities comprising a conveyer for 130

- the band-straw, means for initially compacting and shaping the band, twister mechanism for twisting the compacted and shaped band, means for severing a band length from the 5 twisted band, a band-carrier to deliver the severed and twisted band length to the sheaf, means for tying said band length about the sheaf, a tucker-carriage, means for moving said carriage toward and from the sheaf, an 10 oscillating tucker-head on said carriage, means for directing the tying twist of the band to said tucker-head, means for supporting the portion of the tied band to be tucked in front of the tucker-head, and a band-folding finger 15 over which the band is laid by the tucker.
64. In a self-binder harvester, the combination with suitable grain-cutting and sheaf-forming apparatus, of band forming and tying instrumentalities comprising a conveyer for 20 the band-straw, means for initially compacting and shaping the band, twister mechanism for twisting the compacted and shaped band, means for severing a band length from the twisted band, a band-carrier to deliver the 25 severed and twisted band length to the sheaf, means for tying said band length about the sheaf, a tucker-carriage, means for moving said carriage toward and from the sheaf, an oscillating tucker-head on said carriage, band- 30 directing fingers to direct the tying twist of the band to said tucker-head, band-supporting fingers to support the portion of the band to be tucked in front of the tucker-head, and a band-folding finger over which the band is 35 laid by the tucker.
65. In a self-binder harvester, the combination with suitable grain-cutting and sheaf-forming apparatus, of band forming and tying instrumentalities comprising a conveyer for 40 the band-straw, means for initially compacting and shaping the band, twister mechanism for twisting the compacted and shaped band, means for severing a band length from the twisted band, a band-carrier to deliver the 45 severed and twisted band length to the sheaf, means for tying said band length about the sheaf, a tucker-carriage, means for moving said carriage toward and from the sheaf, an oscillating tucker-head on said carriage, fixed 50 band-directing fingers to direct the tying twist of the band to said tucker-head, movable band-supporting fingers to support the portion of the band to be tucked in front of the tucker-head, means for moving said sup- 55 porting-fingers into operative position, and a band-folding finger over which the band is laid by the tucker.
66. In a self-binder harvester, the combination with suitable grain-cutting and sheaf-forming apparatus, of band forming and tying instrumentalities comprising a conveyer for the band-straw, means for initially compacting and shaping the band, twister mechanism for twisting the compacted and shaped 65 band, means for severing a band length from
- the twisted band, a band-carrier to deliver the severed and twisted band length to the sheaf, means for tying said band length about the sheaf, a tucker-carriage, means for moving said carriage toward and from the sheaf, an 70 oscillating tucker-head on said carriage, fixed band-directing fingers to direct the tying twist of the band to said tucker-head, movable band-supporting fingers to support the portion of the band to be tucked in front of the tucker-head, means for moving said supporting-fingers, and a yielding band-folding finger over which the band is laid by the tucker. 75
67. In a self-binder harvester, the combination with suitable grain-cutting and sheaf-forming apparatus, of band forming and tying instrumentalities comprising a conveyer for the band-straw, means for initially compacting and shaping the band, twister mech- 80 anism for twisting the compacted and shaped band, means for severing a band length from the twisted band, a band-carrier to deliver the severed and twisted band length to the sheaf, means for tying said band length about the sheaf, a tucker-carriage, means for moving said carriage toward and from the sheaf, an oscillating tucker-head on said carriage, fixed band-directing fingers to direct the tying twist of the band to said tucker-head, mov- 85 able band-supporting fingers to support the portion of the band to be tucked in front of the tucker-head, means for moving said sup- porting-fingers, a pivoted folding-finger over which the band is laid by the tucker, and 90 means for moving said band-folding finger into operative position. 95
68. In a self-binder harvester, the combination with suitable grain-cutting and sheaf-forming apparatus, of band-forming and tying 100 instrumentalities comprising a conveyer for the band-straw, means for initially compacting and shaping the band, twister mechanism for twisting said compacted and shaped band, means for severing a band length from the twisted band, a band-carrier to deliver the 105 severed and twisted band length to the sheaf, means for tying said band length about the sheaf, a tucker-carriage, means for moving said carriage toward and from the sheaf, an oscillating tucker-head on said carriage, fixed 110 band-directing fingers to direct the tying twist of the band to said tucker-head, movable band-supporting fingers to support the portion of the band to be tucked in front of the tucker-head, means for moving said sup- 115 porting-fingers, a pivoted spring-supported band-folding finger over which the band is laid by the tucker, and means for moving said band-folding finger into operative position. 120
69. In a self-binder harvester, the combination with suitable grain-cutting and sheaf-forming apparatus, of band forming and tying instrumentalities comprising a conveyer for the band-straw, means for initially compact- 125
- 130

ing and shaping the band, twister mechanism for twisting the compacted and shaped band, means for severing a band length from the twisted band, a band-carrier to deliver 5 the severed and twisted band length to the sheaf, means for tying said band length about the sheaf, a tucker-carriage, means for moving said carriage toward and from the sheaf, an oscillating tucker-head on said carriage, 10 means for directing the tying twist of the band to said tucker-head, means for supporting the portion of the band to be tucked in front of the tucker-head, and a tuck-piercing prong to hold the tuck during the withdrawal 15 of the tucker.

70. In a self-binder harvester, the combination with suitable grain-cutting and sheaf-forming apparatus, of band forming and tying instrumentalities comprising a conveyer for 20 the band-straw, means for initially compacting and shaping the band, twister mechanism for twisting the compacted and shaped band, means for severing a band length from the twisted band, a band-carrier to deliver the 25 severed and twisted band length to the sheaf, means for tying said band length about the sheaf, a tucker-carriage, means for moving said carriage toward and from the sheaf, an oscillating tucker-head on said carriage, means 30 for directing the tying twist of the band to said tucker-head, means for supporting the portion of the band to be tucked in front of the tucker-head, a pivoted tuck-piercing prong to hold the tuck during withdrawal of the 35 tucker, and means for actuating said tuck-piercing prong.

71. In a self-binder harvester, the combination with suitable grain-cutting and sheaf-forming apparatus, of band forming and tying 40 instrumentalities comprising a conveyer for the band-straw, means for initially compacting and shaping the band, twister mechanism for twisting the compacted and shaped band, means for severing a band length from the 45 twisted band, a band-carrier to deliver the severed and twisted band length to the sheaf, means for tying said band length about the sheaf, a tucker-carriage, means for moving said carriage toward and from the sheaf, an 50 oscillating tucker-head on said carriage, means for directing the tying twist of the band to said tucker-head, means for supporting the portion of the band to be tucked in front of the tucker-head, a pivoted spring-retracted 55 tuck-piercing prong to hold the tuck during withdrawal of the tucker, and means for actuating said tuck-piercing prong to pierce the tuck.

72. In a self-binder harvester, the combination with suitable grain cutting and conveying apparatus, of a sheaf-cradle to receive the grain to be bound, means for binding the sheaf, and means for lowering the cradle away from the binding mechanism during the binding 65 operation.

73. In a self-binder harvester, the combination with suitable grain cutting and conveying apparatus, of a two-part sheaf-cradle to receive the grain to be bound, means for binding the sheaf, and means for lowering the said two-part cradle away from the binding mechanism during the binding operation. 70

74. In a self-binder harvester, the combination with suitable grain cutting and conveying apparatus, of a two-part sheaf-cradle to receive the grain, means for raising and lowering the two parts of said cradle independently of each other, and means for binding the sheaf. 75

75. In a self-binder harvester, the combination with suitable grain cutting and conveying apparatus, of a two-part sheaf-cradle to receive the grain, means for raising and lowering the two parts of said cradle independently of each other, packer devices to pack the grain into said cradle, and means for binding 80 the sheaf. 85

76. In a self-binder harvester, the combination with suitable grain cutting and conveying apparatus, of a two-part sheaf-cradle to receive the grain, means for raising and lowering the two parts of said cradle independently of each other, packer devices to pack the grain into said cradle, a compressor to compress and hold the sheaf during binding, and means for binding the sheaf. 90

77. In a self-binder harvester, the combination with a two-part sheaf-cradle to receive the cut grain, a traveling band-carrier to lay the band beneath the sheaf, and independently and vertically movable supports for the two parts 100 of said cradle, whereby one cradle part may be raised out of the line of travel of said band-carrier independently of the other. 95

78. In a self-binder harvester, the combination with a two-part sheaf-cradle to receive 105 the cut grain, a traveling band-carrier to lay the band beneath the sheaf, and independently movable, tilting beams forming supports for the two parts of said cradle, whereby one cradle part may be raised out of the line of 110 travel of said band-carrier independently of the other.

79. In a self-binder harvester, the combination with suitable grain cutting and conveying apparatus, of a sheaf-cradle to receive the 115 grain, said cradle being made up of independently and vertically movable parts, means for binding the sheaf, and means for tilting the two parts of said cradle simultaneously to eject the bound sheaf. 120

80. In a self-binder harvester, the combination with suitable grain cutting and conveying apparatus, of a sheaf-cradle to receive the grain, said cradle being made up of independently and vertically movable parts, means for binding the sheaf, means for tilting the two parts of said cradle simultaneously to eject the bound sheaf, and means actuated by the tilting of the cradle to throw the sheaf from 125 said two-part tilted cradle. 130

81. In a self-binder harvester, the combination with suitable grain cutting and conveying apparatus, of a sheaf-cradle to receive the grain formed of two pairs of substantially 65
5 U-shaped arms, independently and vertically movable rocking supports for each of said pairs of arms, means for binding the sheaf, and means for simultaneously tilting said rocking supports to eject the bound sheaf from
10 the cradle.
82. In a self-binder harvester, the combination with suitable grain cutting and conveying apparatus, of a two-part sheaf-cradle, the two parts of which are independently and vertically 70
15 movable, independent vertically-movable rocking supports for the cradle parts, means for tilting one of said cradle parts, and connections between said tilted part and the other half of the cradle to effect a simultaneous tilting thereof and eject the bound
20 sheaf.
83. In a self-binder harvester, the combination with suitable grain cutting and conveying apparatus, of a two-part tilting sheaf-cradle to receive the grain, the parts of the cradle being independently and vertically movable, means for binding the sheaf, means for simultaneously tilting the cradle parts to eject the bound sheaf, and pivoted sheaf-throwing 80
25 arms operable automatically upon tilting of the cradle parts to throw the sheaf from the two-part cradle.
84. A sheaf-compressor for self-binder harvesters comprising a spring-arm, sheaf-straddling arms carried thereby, and a rigid arm to form an abutment for said spring-arm. 85
30
85. Sheaf-compressor mechanism for self-binder harvesters, comprising a spring pressure-arm, a rigid abutment therefor, sheaf-straddling arms carried thereby, means for throwing said pressure-arm to compressing position, and means for locking it in such position.
86. Sheaf-compressor mechanism for self-binder harvesters, comprising a spring pressure-arm, a rigid abutment therefor, sheaf-straddling arms carried thereby, means for holding said pressure-arm in upright inactive 90
45 position, means for intermittently throwing said arm to compressing position, and means for locking it in such position.
87. Sheaf-compressor mechanism for self-binder harvesters, comprising a spring pressure-arm, a rigid abutment therefor, sheaf-straddling arms carried thereby, a spring normally holding said pressure-arm in upright inactive position, means for automatically throwing said arms to compressing position at predetermined intervals, means for locking said arm in such position, and means for automatically releasing said arm.
88. Sheaf-compressor mechanism for self-binder harvesters, comprising a spring-lifted spring pressure-arm, a rigid abutment there- 95

- for, means for throwing said arm to compressing position against the stress of its lifting-spring, and a latch to engage and lock said arm in compressing position.
89. Sheaf-compressor mechanism for self-binder harvesters, comprising a spring-lifted 70
75 spring pressure-arm, a rigid abutment therefor, means for throwing said arm to compressing position against the stress of its lifting-spring, a latch to engage and lock said arm in compressing position, and means for automatically throwing said latch at predetermined intervals to permit said spring-lifted arm to return to normal position.
90. Sheaf-compressing and band-tucking mechanism for self-binder harvesters, comprising a pressure-arm, sheaf-straddling arms carried thereby, sheaf-piercing prongs or pins on said straddling-arms to form band-stops to prevent movement of the band lengthwise of the sheaf during tucking, and a band-tucking blade which plays between said sheaf-piercing prongs or pins in making its tucking thrust.
91. A sheaf-compressor for self-binder harvesters comprising a pressure-arm having a 90
95 forked forward end to receive the tucking-blade during the tucking operation, and sheaf-straddling arms on said pressure-arm.
92. In a self-binder harvester, the combination with suitable grain cutting and conveying apparatus, of an inclined grain-deck having a transverse slot or opening therein, a pivoted bail having a downwardly-turned end adapted to enter said slot and check the flow of grain down the deck, and means for intermittently swinging said bail, away from the deck to release the accumulated grain.
93. In a self-binder harvester, the combination with suitable grain-cutting apparatus, of band-straw-handling instrumentalities comprising a conveyer which receives the band-straw as it falls before the cutting apparatus, and separator-boards to separate that portion of the standing grain which is to form the band-straw from the bulk of the grain and direct it to the said conveyer.
94. In a self-binder harvester, the combination with suitable grain-cutting apparatus, of band-straw-handling instrumentalities comprising a conveyer which receives the band-straw as it falls before the cutting apparatus, and vertically-adjustable separator-boards to separate that portion of the standing grain which is to form the band-straw from the bulk of the grain and direct it to the said conveyer.
95. In a self-binder harvester, the combination with suitable grain-cutting apparatus, of band-straw-handling instrumentalities comprising a conveyer which receives the band-straw as it falls before the cutting apparatus, and separator-boards having vertically-adjustable front sections, to separate that portion

tion of the standing grain which is to form the band-straw from the bulk of the grain and direct it to the said conveyer.

96. In a self-binder harvester, the combination with suitable grain cutting and conveying apparatus, of band-straw-handling instrumentalities comprising an independent conveyer which receives the band-straw as it falls before the cutting apparatus, separator-boards to separate that portion of the standing grain which is to form the band-straw from the bulk of the grain and direct it to the said conveyer, and means for adjusting one of said separator-boards horizontally relative to the other.
- 10 97. In a self-binder harvester, the combination with suitable grain cutting and conveying apparatus, of band-straw-handling instrumentalities comprising an independent conveyer which receives the band-straw as it falls before the cutting apparatus, and separator-boards to separate that portion of the standing grain which is to form the band-straw from the bulk of the grain and direct it to said conveyer, one of said separator-boards being 20 pivoted at its rear end so as to be horizontally adjustable relative to its fellow.
- 15 98. In a self-binder harvester, the combination with suitable grain-cutting apparatus, of band-straw-handling instrumentalities comprising a conveyer which receives the band-straw as it falls before the cutting apparatus, separator-boards to separate the band-straw from the bulk of the grain and direct it to said conveyer, and pick-up devices to straighten 25 the grain for delivery to the said conveyer.

99. In a self-binder harvester, the combination with suitable grain-cutting apparatus, of band-straw-handling instrumentalities comprising a conveyer which receives the band-straw as it falls before the cutting apparatus, separator-boards to separate the band-straw from the bulk of the grain and direct it to said conveyer, and pick-up devices carried by said separator-boards to straighten the grain for 40 delivery to the said conveyer.

100. In a self-binder harvester, the combination with suitable grain-cutting apparatus, of band-straw-handling instrumentalities comprising a conveyer to receive the band-straw as it falls before the cutting apparatus, separator-boards having vertically-adjustable front sections to separate the band-straw from the bulk of the grain and direct it to said conveyer, means for adjusting one of said separator-boards horizontally relative to the other, and pick-up chains carried by said separator-boards to straighten the grain for delivery to the said conveyer.

101. In a self-binder harvester, the combination with suitable cutting apparatus, of a conveyer for the band-straw, and a receiving-spout into which said conveyer delivers, the side walls of said spout extending beyond the top and bottom walls so as to embrace the delivery end of the conveyer, the top wall of

said spout having an upwardly-flared extension to give an enlarged receiving-mouth.

102. In a self-binder harvester, the combination with suitable cutting apparatus, of a conveyer for the band-straw, and a receiving-spout into which said conveyer delivers, said spout having an upwardly-flaring mouth and a laterally-curved delivery end.

103. In a self-binder harvester, the combination with suitable cutting apparatus, of a conveyer for the band-straw, and a receiving-spout into which said conveyer delivers, said spout having an upwardly-flaring mouth and a reduced and laterally-curved delivery end.

104. In a self-binder harvester, the combination with suitable cutting apparatus, of a conveyer for the band-straw, and a receiving-spout into which said conveyer delivers, said spout having one of its side walls at its delivery end cut away.

105. In a self-binder harvester, the combination with suitable cutting apparatus, of a conveyer for the band-straw, and a receiving-spout into which said conveyer delivers, said spout having an upwardly-flaring mouth and a reduced laterally-curved delivery end, one of the side walls at the delivery end of the spout being cut away.

106. In a self-binder harvester, the combination with suitable cutting apparatus, of a conveyer for the band-straw, chains to initially compress and shape the band which receive the straw from said conveyer, and guides to maintain the inner runs of said chains in compressing proximity to each other.

107. In a self-binder harvester, the combination with suitable cutting apparatus, of a conveyer for the band-straw, interlocking chains to initially compress and shape the band which receive the straw from the said conveyer, guides to maintain the inner runs of said chains in compressing proximity to each other, and supporting-rails for the outer runs of said interlocking chains.

108. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a reciprocating band-severing knife to sever a band length from the continuous band, means for holding the knife at a cutting angle to the band during its forward thrust, and means for moving said knife out of the way of the band during its return movement.

109. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a reciprocating spring-actuated band-severing knife to sever a

band length from the continuous band, means for automatically retracting said knife and putting its actuating-spring under tension at predetermined intervals, means for holding the knife at a cutting angle to the band during its forward thrust, and means for moving said knife out of the way of the band during its return movement.

110. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a reciprocating spring-actuated band-severing knife to sever a band length from the continuous band, means for automatically retracting said knife and putting its actuating-spring under tension at predetermined intervals, a spring for holding the knife at a cutting angle to the band during its forward thrust, and means for depressing said knife below said band during its return movement.

25 111. In a self-binder harvester, the combination with suitable grain-cutting and sheaf-forming apparatus, of instrumentalities for making a continuous straw band, band grasping and carrying devices to seize a band length
30 as the continuous band comes from the band-making instrumentalities, a reciprocating knife-bar, means for giving a cutting thrust to said knife-bar, means for retracting said knife-bar, a severing-knife pivoted at the forward end of said bar, and means for maintaining said blade at a cutting angle to the band.
35

112. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a reciprocating knife-bar, a spring for giving a cutting thrust to said knife-bar, means for retracting said knife-bar and compressing said spring, a severing-knife pivoted at the forward end of said bar, and means for maintaining said blade at a cutting angle to the band.

113. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a reciprocating knife-bar, a spring for giving a cutting thrust to said knife-bar, means for retracting said knife-bar and compressing said spring, a severing-knife pivoted at the forward end of said bar, and a spring for maintaining said blade at a cutting angle to the band.

114. In a self-binder harvester, the combination with suitable grain-cutting and sheaf-

forming apparatus, of instrumentalities for
making a continuous straw band, band grasp-
ing and carrying devices to seize a band length
as the continuous band comes from the band-
making instrumentalities, a reciprocating 70
knife-bar, a spring for giving a cutting thrust
to said knife-bar, means for retracting said
knife-bar and compressing said spring, a sever-
ing-knife pivoted at the forward end of
said bar, a spring for maintaining said blade 75
at a cutting angle to the band, and means for
depressing said blade below the band during
the retraction of the knife-bar.

115. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a bed-plate having 85 a band-opening therein, a reciprocating knife, means for impelling said knife across the bed-plate opening with a cutting thrust, means for retracting the knife, and means for depressing said knife below the moving band 90 during such retraction.

116. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a bed-plate having a band-opening therein, an inclined reciprocating knife, means for impelling said knife across the bed-plate opening with a cutting thrust, means for retracting the knife, and means for depressing said knife below the moving band during such retraction. 95 100

117. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a bed-plate having a band-opening therein, an inclined reciprocating knife, a spring for maintaining said knife in inclined position, means for impelling said knife across the bed-plate opening with a cutting thrust, means for retracting the knife, and means for depressing said spring-supported knife below the moving band during such retraction. 105 110 115

118. In a self-binder harvester, the combination with suitable grain-cutting and sheaf-forming apparatus, of instrumentalities for making a continuous straw band, band grasping and carrying devices to seize a band length as the continuous band comes from the band-making instrumentalities, a bed-plate having a band-opening therein, an inclined reciprocating knife, a spring for maintaining said knife in inclined position, means for impelling said knife across the bed-plate opening with a cut- 120 125 130

ting thrust, means for retracting the knife, and means on said bed-plate for depressing said spring-supported knife below the moving band during such retraction.

- 5 119. In a self-binder harvester, the combination with suitable grain-cutting and sheaf-forming apparatus, of instrumentalities for making a continuous straw band, band grasping and carrying devices to seize a band length 65 as the continuous band comes from the band-making instrumentalities, a bed-plate having a band-opening therein, a pivoted knife, a spring for maintaining said knife in cutting position, means for reciprocating said knife, 70 a fixed guide on said bed-plate to hold said pivoted knife in cutting position during the forward movement of the knife, and a pivoted spring-guide on said bed-plate to depress said pivoted blade below said bed-plate opening 75 during the retraction of the knife.

- 10 120. In a self-binder harvester, the combination with suitable grain-cutting and sheaf-forming apparatus, of instrumentalities for making a continuous straw band, band grasping and carrying devices to seize a band length 80 as the continuous band comes from the band-making instrumentalities, a bed-plate having a band-opening therein, an inclined pivoted knife, means for moving said knife across the band-opening to make a severing cut, means for retracting said knife, and a guide on said bed-plate to depress said pivoted knife below said opening 85 during its return movement.

- 15 121. In a self-binder harvester, the combination with suitable grain-cutting and sheaf-forming apparatus, of instrumentalities for making a continuous straw band, band grasping and carrying devices to seize a band length 90 as the continuous band comes from the band-making instrumentalities, a bed-plate having a band-opening therein, an inclined pivoted knife, means for moving said knife across the band-opening to make a severing cut, means for retracting said knife, and a guide on said bed-plate to depress said pivoted knife below 95 said opening during its return movement.

- 20 122. In a self-binder harvester, the combination with suitable grain-cutting and sheaf-forming apparatus, of instrumentalities for making a continuous straw band, band grasping and carrying devices to seize a band length 100 as the continuous band comes from the band-making instrumentalities, a bed-plate having a band-opening therein, a pivoted knife, a spring for maintaining said knife in cutting position, means for reciprocating said knife, 105 a guide on said bed-plate to hold said pivoted knife in cutting position during the forward movement of the knife, and a guide on said bed-plate to depress said pivoted blade below said bed-plate opening during the retraction of the knife.

- 25 123. In a self-binder harvester, the combination with suitable grain-cutting and sheaf-forming apparatus, of instrumentalities for making a continuous straw band, band grasping 110

ing and carrying devices to seize a band length 65 as the continuous band comes from the band-making instrumentalities, a bed-plate having a band-opening therein, a pivoted knife, a spring for maintaining said knife in cutting position, means for reciprocating said knife, 70 a fixed guide on said bed-plate to hold said pivoted knife in cutting position during the forward movement of the knife, and a pivoted spring-guide on said bed-plate to depress said pivoted blade below said bed-plate opening 75 during the retraction of the knife.

124. In a self-binder harvester, the combination with suitable grain-cutting and sheaf-forming apparatus, of instrumentalities for making a continuous straw band, band grasping and carrying devices to seize a band length 80 as the continuous band comes from the band-making instrumentalities, a bed-plate having a band-opening therein, a pivoted spring-supported knife-blade, means for reciprocating 85 said knife-blade across said band-opening with a severing cut, a guiding-rib on said bed-plate against which the pivoted knife rides in its forward movement and a yielding guide which permits said knife to move forward across 90 the band-opening with a cutting thrust, but depresses said pivoted knife below said opening on its return movement.

125. In a self-binder harvester, the combination with a sheaf-cradle, of band-carrier 95 supporting tracks adjacent said cradle, a reciprocating band-carrier adapted to seize a band and move it to a predetermined position at right angles to said sheaf-cradle mounted on said tracks, means for reciprocating said 100 carrier, band-grasping jaws on said carrier, and means for opening said jaws at the limit of forward movement of said carrier.

126. In a self-binder harvester, the combination with suitable supporting-tracks, of a 105 traveling band-carrier mounted on said tracks, means for reciprocating said band-carrier, spring-closed band-grasping jaws on said band-carrier, means for opening said jaws at the limit of the forward movement of said 110 carrier, and independent means to hold the band against movement lengthwise of the jaws.

127. In a self-binder harvester, the combination with suitable supporting-tracks, of a 115 traveling band-carrier mounted on said tracks, means for reciprocating said band-carrier, spring-closed band-grasping jaws on said band-carrier, means for opening said jaws at the limit of the forward movement of said 120 carrier, and band-pinchng fingers to hold the band against movement lengthwise of the jaws.

128. In a self-binder harvester, the combination with a sheaf-cradle, of band-carrier 125 supporting tracks adjacent said cradle, a reciprocating band-carrier adapted to seize a band and move it to a predetermined position

at right angles to said sheaf-cradle mounted on said tracks, band-grasping jaws on said carrier to seize a band at each end, and means for supporting the band intermediate its ends.

5 129. In a self-binder harvester, the combination with suitable supporting-tracks, of a traveling band-carrier mounted on said tracks, band-grasping jaws on said carrier to seize a band at each end, means for opening said jaws, 10 and a swinging bail connecting said jaws to support the band intermediate its ends.

129. In a self-binder harvester, the combination with suitable supporting-tracks, of a traveling band-carrier, mounted on said tracks 15 and comprising fixed band-grasping jaws, movable band-grasping jaws, means for opening said movable jaws at the limit of forward movement of the carrier, and a swinging bail operable from said movable jaws to lift and 20 support the band intermediate its ends.

131. In a self-binder harvester, the combination with suitable supporting-tracks, of a traveling band-carrier mounted on said tracks and comprising fixed and movable jaws, inclining lifting-rails at the forward ends of said supporting-tracks to open said movable jaws, band-pinching fingers operable from said movable jaws to hold the band from moving lengthwise between the jaws, and a swinging bail 30 connected with said movable jaws to support the band intermediate its ends.

132. In a self-binder harvester, the combination with suitable supporting-tracks, of a traveling band-carrier mounted on said tracks 35 and comprising fixed and movable jaws, springs to normally close said movable jaws, inclined hinged lifting-rails at the forward ends of said supporting-tracks to open said movable jaws during the forward movement 40 of the carrier, band-pinching fingers operable from said movable jaws to hold the band from moving lengthwise between the jaws, and a swinging bail connected with and operable by said movable jaws to support the band intermediate its ends.

133. In a self-binder harvester, the combination with suitable supporting-tracks, of a traveling band-carrier mounted on said tracks and comprising band-grasping jaws, means 50 for holding said jaws normally closed, means for opening said jaws at a predetermined time, means for reciprocating said carrier, means for locking said carrier against reciprocation, and connections between said carrier-reciprocating means and the power-shaft 55 of the harvester to automatically unlock and reciprocate the carrier at predetermined times.

134. In a self-binder harvester, the combination with suitable supporting-tracks, of a traveling band-carrier mounted thereon, band-grasping devices on said carrier, means for reciprocating said carrier, means for locking said carrier, driving connections between said

carrier-reciprocating means and the power-shaft of the harvester to reciprocate the carrier at predetermined times, and means to automatically unlock the carrier. 65

135. Band-tying mechanism for self-binder harvesters, comprising a vertically-movable support, means for raising and lowering said support, sheaf-straddling arms pivoted on said support, means for opening and closing said arms, means for positively locking said arms as they rise to closed position above the sheaf, and 70 band-grasping devices carried by said sheaf-straddling arms. 75

136. Band-tying mechanism for self-binder harvesters, comprising a vertically-movable support, means for raising and lowering said support, sheaf-straddling arms pivoted to said support, means for automatically opening said arms as the support falls and closing them as it rises, independent means to positively lock 80 said arms in closed position above the sheaf, band-grasping hands pivoted on said arms, and means for automatically opening and closing 85 said hands.

137. Band-tying mechanism for self-binder harvesters, comprising a vertically-movable support, means for raising and lowering said support, sheaf-straddling arms pivoted to said support, means for automatically opening said arms as the support falls and closing them as it rises, independent means to positively lock 90 said arms in closed position above the sheaf, spring-closed band-grasping hands pivoted on said arms, and means for opening said spring-closed hands. 95

138. Band-tying mechanism for self-binder harvesters, comprising a vertically-movable support, means for raising and lowering said support, sheaf-straddling arms pivoted to said support, means for opening said arms as the support falls and closing them as it rises, independent means for positively locking said 100 arms in closed position above the sheaf, band-grasping hands pivoted on said arms, springs to hold said arms normally closed, hand-actuating devices carried by said arms, and means 105 for operating said actuating devices to throw the hands to band-grasping position as the sheaf-straddling arms descend. 110

139. Band-tying mechanism for self-binder harvesters, comprising a vertically-movable support, means for raising and lowering said support, sheaf-straddling arms pivoted on said support, stationary guides engaging the upper ends of said pivoted arms to open said arms as they fall and close them as they rise, independent means for positively locking said arms in their upper closed position, spring-closed band-grasping hands pivoted to said arms, sliding frames mounted on said arms and engaging said pivoted hands, and means 115 to arrest the movement of said sliding frames and actuate said band-grasping hands as the sheaf-straddling arms descend. 120

140. Band-tying mechanism for self-binder harvesters comprising a rising and falling support, means for raising and lowering said support, sheaf-straddling arms pivoted on said support, means for opening said arms as the support falls and closing them as it rises, independent means for positively locking said arms in their upper closed position, band-grasping hands pivoted on said arms, springs to normally close said hands, hand-actuating devices to open said hands as the sheaf-straddling arms descend, and means for rotating said rising and falling support and the parts carried thereby.
141. Band-tying mechanism for self-binder harvesters, comprising a vertically-movable rack, means for raising and lowering said rack, a rotary shaft carried by said rack, a pinion splined on said shaft, means for rotating said pinion and shaft, sheaf-straddling arms pivoted on said shaft, means for opening and closing said arms, and band-grasping hands carried by said arms.
142. Band-tying mechanism for self-binder harvesters, comprising a vertically-movable rack, means for raising and lowering said rack, a rotary shaft carried by said rack, a pinion splined on said shaft, means for locking said rack and shaft in raised position, means for rotating said pinion and shaft, sheaf-straddling arms pivoted on said shaft, means for opening and closing said arms, and band-grasping hands carried by said arms.
143. Band-tying mechanism for self-binder harvesters, comprising a stationary support, a vertically-movable rack mounted thereon, a rotary shaft carried by said rack, a pinion mounted on said stationary support and splined to said shaft, means for locking said rack and shaft in raised position, sheaf-straddling arms carried by said support, a rotatable plate suspended from said stationary support, guides to open and close said sheaf-straddling arms carried by said rotatable plate, means for locking said arms to said rotatable plate in their raised position, spring-closed band-grasping hands pivotally mounted on said arms, means for opening said hands as the sheaf-straddling arms descend, means for locking said rotatable plate, means for automatically releasing said plate, and means for rotating said pinion, shaft and the suspended parts.
144. Band-tying mechanism for self-binder harvesters, comprising hands movable toward and from each other, said hands having semitubular band-grasping members to grasp and hold in twisted condition a twisted straw band, and means for rotating said hands to tie the twisted band.
145. Band-tying mechanism for self-binder harvesters comprising hands movable toward and from each other, said hands having semitubular band-grasping members to grasp and hold in twisted condition a twisted straw band, interlocking fingers on said members to prevent accidental withdrawal of the band during the tying operation, and means for rotating said hands to tie the twisted band.
146. Band-tying mechanism for self-binder harvesters comprising hands movable toward and from each other, said hands having semitubular band-grasping members carried by said hands to grasp and hold in twisted condition a twisted straw band, interlocking fingers on said members to prevent accidental withdrawal of the band during the tying operation, means for guiding said members in their movements toward and from each other, and means for rotating said hands to tie the twisted band.
147. Band-tying mechanism for self-binder harvesters comprising pivoted hands having semitubular band-grasping members, interlocking fingers on said members, means for guiding said pivoted hands and holding the band centrally between said grasping members, and means for rotating said hands to tie the band.
148. Band-tying mechanism for self-binder harvesters, comprising pivoted hands having semitubular band-grasping members to seize and hold in twisted condition a twisted straw band, interlocking fingers on said hands to prevent accidental withdrawal of the band during the tying operation, a substantially T-shaped guide for said members in their movements toward and from each other, said guide serving also to center the band between the band-grasping members, and means for rotating said hands to tie the twisted band.
149. Band-tucking mechanism for self-binder harvesters comprising supporting-tracks, a tucker-carriage movable on said tracks toward and from the sheaf, means including a gear-segment engaging a rack on said carriage for reciprocating said carriage to and from tucking position and holding it stationary in its forward tucking position for a predetermined period, and band-tucking devices carried by said reciprocating tucker-carriage.
150. Band-tucking mechanism for self-binder harvesters, comprising supporting-tracks, a tucker-carriage movable on said tracks toward and from the sheaf, means including a gear-segment engaging a rack on said carriage for reciprocating said carriage to and from the tucking position and holding it stationary in its forward tucking position for a predetermined period, a tucking-blade mounted on said carriage, means for operating said blade to make the tuck as the carriage moves forward, means for withdrawing said blade as the carriage is retracted, and means for holding the tucked band during withdrawal of the blade.
151. Band-tucking mechanism for self-binder harvesters comprising supporting-tracks, a tucker-carriage movable on said tracks toward and from the sheaf, means in-

- cluding a gear-segment engaging a rack on said carriage for reciprocating said carriage to and from tucking position and holding it stationary in its forward tucking position for 5 a predetermined period, a curved tucking-blade mounted on said carriage, means for rocking said blade to make the tuck when the carriage is in its forward position, means for withdrawing said blade, and means for holding the tucked band during withdrawal of the blade.
152. Band - tucking mechanism for self-binder harvesters comprising supporting-tracks, a tucker - carriage movable on said tracks toward and from the sheaf, means including a gear-segment engaging a rack on said carriage for reciprocating said carriage to and from tucking position and holding it in its forward tucking position for a predetermined period, an oscillating tucker-shaft mounted on said carriage, a curved tucking-blade on said shaft, means for rocking said shaft and blade to make the tuck when the carriage is in its forward position, and means for reversing the movement of the shaft to withdraw the blade.
153. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft mounted on said carriage, a tucker-blade mounted on said shaft, means for rocking said shaft and blade to make the tuck, and a spring for reversing the movement of said shaft to withdraw the blade.
154. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft mounted on said carriage, a tucker-blade adjustably mounted on said shaft, means for rocking said shaft and blade to make the tuck, and a spring for reversing the movement of said shaft to withdraw the blade.
155. Band - tucking mechanism for self-binder harvesters, comprising suitable supporting-tracks, a tucker-carriage mounted thereon, means for reciprocating said carriage, means for locking said carriage in its forward position, an oscillating tucker-shaft on said carriage, a tucker-blade carried by said shaft, means for oscillating said shaft, movable band-supporting fingers mounted on said carriage, and means, operable from a fixed stop on the harvester-frame, to move 55 said supporting-fingers in front of said tucker-blade as the carriage moves forward.
156. Band - tucking mechanism for self-binder harvesters, comprising suitable supporting-tracks, a tucker-carriage mounted thereon, means for reciprocating said car-
- riage, means for locking said carriage in its forward position, an oscillating tucker-shaft on said carriage, a tucker-blade carried by said shaft, movable band-supporting fingers mounted on said carriage, and means for operating said fingers, a movable band-folding finger, and means for moving said folding-finger in front of the band.
157. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft on said carriage, a tucker-blade carried by said shaft, a gear-plate pivoted on said carriage, band-supporting fingers on said gear-plate, a sliding rack meshing with said gear-plate, means for actuating said rack to rotate said plate and move said supporting-fingers in front of the tucker-blade as the carriage runs forward, and means for returning said rack and retracting said fingers on the return movement of the carriage.
158. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft on said carriage, a tucker-blade carried by said shaft, a gear-plate pivoted on said carriage, band-supporting fingers on said gear-plate, a sliding rack meshing with said gear-plate, a weighted rack-operating lever to normally hold said plate and band-supporting arms in retracted position, and a fixed stop to engage said lever as the carriage runs forward and operate said rack and gear-plate.
159. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft on said carriage, a tucker-blade carried by said shaft, movable band-supporting fingers to support the band above and below the path of the tucker-blade, means for operating said fingers, a movable band-folding finger, and means for moving said folding-finger in front of the band.
160. Band - tucking mechanism for self-binder harvesters, comprising suitable supporting-tracks, a tucker-carriage mounted on said tracks, means for reciprocating said carriage, means for locking said carriage in its forward position, an oscillating tucker-shaft on said carriage, a tucker-blade carried by said shaft, movable band-supporting fingers to support the band above and below the path of the tucker-blade, means for operating said

fingers, a movable yielding band-folding finger, and means for moving said yielding folding-finger in front of the band.

161. Band - tucking mechanism for self-
5 binder harvesters, comprising suitable sup-
porting-tracks, a tucker-carriage mounted on
said tracks, means for reciprocating said car-
riage, means for locking said carriage in its
forward position, an oscillating tucker-shaft
10 on said carriage, a tucker-blade carried by said
shaft, band - supporting fingers movable to-
ward and from the tucker-blade, a yielding
band-folding finger movable toward and from
the tucker-blade, a tuck - holding prong to
15 pierce and hold the tuck during withdrawal
of the tucker-blade, and means, operable from
said tucker-shaft to actuate said tuck-holding
device.
162. Band - tucking mechanism for self-
20 binder harvesters, comprising suitable sup-
porting-tracks, a tucker-carriage mounted on
said tracks, means for reciprocating said car-
riage, means for locking said carriage in its
forward position, an oscillating tucker-shaft
25 on said carriage, a tucker-blade carried by said
shaft, band - supporting fingers movable to-
ward and from the tucker-blade, a yielding
band-folding finger movable toward and from
the tucker-blade, a spring-pressed tuck-hold-
30 ing prong to pierce and hold the tuck during
withdrawal of the tucker-blade, and a cam on
said tucker-shaft to actuate said tuck-holding
device.

163. In a band-tucker for self-binder har-

vesters, the combination with a tucking-blade 35
to tuck the tying-twist of the band beneath
the band proper, of a band-folding finger be-
low the path of movement of the blade over
which the said blade lays the band to form the
band fold. 40

164. In a band-tucker for self-binder har-
vesters, the combination with a tucking-blade,
of a yielding band-folding finger to support
the band below the path of movement of the
blade to form the band fold. 45

165. In a band-tucker for self-binder har-
vesters, the combination with a tucking-blade,
of a yielding band-folding finger movable to-
ward and from said blade to support the band
below the path of movement of the blade to 50
form the band fold, and means for moving
said band-folding finger to and from its op-
erative position.

166. In a band-tucker for self-binder har-
vesters, the combination with a tucking-blade, 55
of a yielding band-folding finger movable to-
ward and from said blade to support the band
below the path of movement of the blade to
form the band fold, means for moving said
band-folding finger to and from its operative 60
position, and means for automatically retract-
ing said finger.

In testimony whereof I affix my signature in
presence of two witnesses.

WILLIAM DOUGLASS.

Witnesses:

A. V. CUSHMAN,
EWELL A. DICK.
